Claims priority, application Germany Oct. 1, 1956

37 Claims. (Cl. 103—162)

My invention relates to devices for reducing noise in hydraulic piston machines operable as motors or pumps, and particularly in machines of the type having a rotating multi-cylinder assembly with reciprocable pistons that rotate together with the cylinder assembly.

The operation of piston machines with a liquid pressure medium requires a periodic on and off connection of the variable-volume cylinder chambers with the hydraulic flow circuit, which causes corresponding pressure variations in these chambers, occurring in most cases at relatively high frequency. The forces acting upon the pistons vary proportionally to the pressure and impose corresponding alternating mechanical stresses upon all components of the piston-machine mechanism including its housing.

In accordance with the elasticity law of the conventional materials, the alternating stresses result in noise-producing oscillations whose intensity is mainly dependent upon the rate of pressure increase and decrease.

Based upon the above-mentioned phenomena, noise reducing devices have been proposed which operate to delay the switching operation of the rotary slide valve used in such machines for controlling the periodic supply and discharge of hydraulic operating medium relative to the variable-volume chambers of the machine cylinders.

2

in the cylinder chamber effects a relatively slow expansion or compression of the enclosed hydraulic medium. The result, under most favorable conditions, is that at the moment when the cylinder chamber starts communicating with the control opening or slot of the rotary valve, there already exists equality of pressure between cylinder chamber and valve slot so that the noise-producing abrupt change in pressure is eliminated to a great extent.

10 However, such optimum conditions are the exception; and a more thorough investigation shows that the angle of rotation of the rotary control valve during which the individual cylinder chambers, under expansion or compression, are to remain closed, should not be constant but, for best results, must vary in dependence upon structural constants as well as upon several variable operating parameters, such as the hydraulic delivery pressure ($p_2 - p_1$) and the stroke ratio (H/H_{max}).

Further dependencies of the magnitude and the sign (+ or -) of the compression angle or expansion angle of the rotary valve control means exist, particularly with piston machines of regulatable piston stroke, in accordance with the particular correlation between the direction of rotation and the direction of hydraulic delivery and 25 the selected operation as a pump or a motor. The latter dependencies comprise eight different operation possibilities of variable operation. These eight different types of machine operation are tabulated in the following table. The symbols used in the table are defined below under 30 the heading "Definitions." The sign (+, -) of the compression angle α_k and the expansion angle α_e denote only the direction of variation of the respective angles but not their absolute magnitude. A noise reducing device, in order to operate satisfactorily, must contain structural 35 means which perform the automatic basic regulation in accordance with the table, and it must also comprise additional devices which automatically determine the absolute magnitude of the angle α_k and α_e required for the necessary equalization of pressures.

These devices prolong the switching or pressure-commutating operation of the slide valve by providing the valve with throttle cross sections. However, such throttle cross sections always cause power losses, and their effect varies with the speed of rotation. For that reason, further means have been proposed which operate to keep the cylinder spaces individually closed over a certain angle of rotation in the range of the dead-center position of the pistons, whereby the simultaneous piston movement

65 In a device for noise reduction, the above-mentioned dependencies must be taken into account insofar as the tabulated controlling magnitudes may occur in the desired particular operation of the machine. Accordingly, proposals have become known which achieve the change in compression or expansion angle of the rotary control valve by correspondingly turning the valve member that carries the control openings or slots. Such devices, however, have the disadvantage of requiring a very compli-

cated construction and exhibiting very difficult pressure sealing problems.

It is further impossible with the known proposals to individually vary the compression and expansion angles by amounts differing from each other. This is so because the members that carry the control openings or valve slots permit only a single angular adjustment to be effective simultaneously for all valve openings. This makes it impossible, for instance, to take into account the fact that the compression chambers in the cylinders are different in the inner and outer dead-center position of the piston respectively.

It is therefore one of the objects of my invention to provide noise reducing devices for rotary cylinder machines of the above-mentioned type, which afford satisfying in a favorable manner all requirements as regards the variable and constant magnitudes upon which the above-mentioned pressure adaptation is predicated, thus permitting a better and more reliable noise reduction than obtainable with the devices heretofore known.

To this end, and in accordance with one of the features of my invention, I provide the control slots (main slots) of the rotary control valve, serving for periodically connecting the individual variable-volume cylinder chambers with the suction and pressure ducts of the control valve, with a number of component openings (hereinafter called "auxiliary slots") located near the respective ends of the valve slots; and I further provide the device with hydraulic valve-type switching devices which automatically vary the opening angle of the rotary control valve by connecting and disconnecting the just-mentioned auxiliary slots relative to the main control slots.

The foregoing and more specific objects, advantages and features of my invention, the essential features being set forth with particularity in the claims annexed hereto, will be apparent from, and will be mentioned in, the following description of the embodiments illustrated on the drawings in which:

Fig. 1 is a schematic sectional view of a multi-cylinder hydraulic machine exemplifying the general kind of machinery with which the invention is applicable; and

Fig. 2 is a top view onto the valve control face of the lower rotary valve member forming part of the machine shown in Fig. 1.

Fig. 3 is a schematic view onto the control slots in the control face of a rotary slide valve, in conjunction with other components of a noise reducing device according to the invention.

Figs. 4, 5 and 6 illustrate schematically three different modifications of such noise reducing devices.

Fig. 7 illustrates schematically a complete control system including the valve control slots and a number of hydraulic switching and pressure regulating components.

Fig. 8 is a modification of a complete system somewhat similar to that of Fig. 7.

Fig. 9 illustrates schematically a multiple valve-type switching device applicable in devices according to the invention.

Fig. 10 illustrates schematically a pressure regulator also for devices according to the invention.

Fig. 11 illustrates schematically another multiple hydraulic switching device.

Fig. 12 illustrates schematically a complete system according to the invention, comprising the valve control slots as well as hydraulic switching and regulating devices.

Fig. 13 shows another complete system similar in kind to those of Figs. 7, 8 and 12.

The same reference characters are used in all illustrations for functionally similar components respectively.

Definitions

The following symbols and abbreviations are used throughout this specification:

p =delivery pressure=pressure difference p_2-p_1

- p_1 =pressure in the suction slot=slot of lower pressure
 p_2 =pressure in the pressure slot=slot of higher pressure
 p_t =control pressure for the piston in the range of the one neutral zone that comprises the inner dead-center position of the piston
 p_a =control pressure for the piston in the range of the other neutral zone comprising the outer dead-center position of the piston
 p_x =pressure of an auxiliary hydraulic path, for instance produced by a leakage oil pump
 p_y =a pressure equal or proportional to the difference pressure p
 p_z =pressure in the cylinder (variable-volume chamber)
 V_R =cylinder volume at $V_R=$ zero (zero stroke adjustment)
 V_{si} =cylinder volume at the inner dead-center point of the piston
 V_{so} =cylinder volume at the outer dead-center position of the piston
20 V_h =stroke volume of a piston at a rotation angle α of the rotary valve slider
 V_R =displacement volume of a piston at full stroke, corresponding to $\alpha=180^\circ$
 $+V_R$ =machine operates clockwise (CL) as a pump, or anti-clockwise (ACL) as a motor; under these conditions p_1 obtains in control slot 1a, and pressure p_2 obtains in control slot 1b
25 $-V_R$ =machine operates clockwise (CL) as motor or anti-clockwise (ACL) as pump; then p_1 obtains in control slot 1a, p_2 in control slot 1b
 α =rotation angle of the rotary slide valve or of the stroke-producing shaft, measured from the dead-center position of the piston
30 α_k =compression angle=rotation angle of the stroke-producing shaft or of the rotary slide valve, during which angle the pressure p_2 increases when the cylinder chamber is closed
 α_k =expansion angle=rotation angle of the stroke-producing shaft or of the rotary slide valve, during which angle the pressure p_2 declines when the cylinder chamber is closed
35 α_1 =rotation angle which results in a displacement volume V_h on the V_{si} -side of the valve control face (measured from the neutral axis)
40 α_2 =rotation angle which results in a volume variation V_h on the V_{so} -side of the valve control face (measured from the neutral axis)
 $+ \alpha_k$ =positive compression angle; i.e. α_k is adjacent to the neutral axis with clockwise (CL) rotation
45 $- \alpha_k$ =negative compression angle; i.e. α_k is adjacent to the neutral axis with anti-clockwise (ACL) rotation
 $+ \alpha_e$ =positive expansion angle; i.e. α_e is adjacent to the neutral axis with clockwise (CL) rotation
 $- \alpha_e$ =negative expansion angle; i.e. α_e is adjacent to the neutral axis with anti-clockwise (ACL) rotation
50 $+ \alpha_{ki}$ =positive compression angle in the range of the inner dead-center point
 $- \alpha_{ki}$ =negative compression angle in the range of the inner dead-center point
 $+ \alpha_{eo}$ =positive compression angle in the range of the outer dead-center point
 $- \alpha_{eo}$ =negative compression angle in the range of the outer dead-center point
55 $+ \alpha_{ei}$ =positive expansion angle in the range of the inner dead-center point
 $- \alpha_{ei}$ =negative expansion angle in the range of the inner dead-center point
 $+ \alpha_{eo}$ =positive expansion angle in the range of the outer dead-center point
 $- \alpha_{eo}$ =negative expansion angle in the range of the outer dead-center point
60 $+ \alpha_{ea}$ =positive expansion angle in the range of the inner dead-center point
 $- \alpha_{ea}$ =negative expansion angle in the range of the outer dead-center point
65 $+ \alpha_{el}$ =positive expansion angle in the range of the inner dead-center point
 $- \alpha_{el}$ =negative expansion angle in the range of the inner dead-center point
 $+ \alpha_{el}$ =positive expansion angle in the range of the outer dead-center point
 $- \alpha_{el}$ =negative expansion angle in the range of the outer dead-center point
70 C_1 =elasticity constant of the liquid working medium
 C_2 =elasticity constant of the cylinder volume V_z including the stroke-producing mechanism component
75

C_s =spring constant of the elastic means, such as springs or the like, with which the reciprocable pistons are loaded

CL =clockwise sense of rotation

ACL =anti-clockwise sense of rotation

NA =neutral axis=imaginary line on the control face of the rotary slide valve which bisects the centering angle of the cylinder port at the moment when the appertaining piston is in a dead-center position

Generally, machines of the type here involved have pistons reciprocating in respective cylinder bores which are distributed about the drive shaft and extend in parallel, inclined or radial relation thereto. The individual cylinders are sequentially connected, in timed relation to the periodic piston reciprocations, with stationary valve slots for supplying and discharging the hydraulic working medium. For this purpose, the member or drum in which the cylinder bores are located is rotatable in face-to-face engagement with a fixed valve surface and is provided with ports which periodically establish a communication between the respective cylinder bores and the valve slots of the fixed valve surface (control face of the valve). The rotating member thus forms together with the fixed valve surface a valve device of the rotary slide-valve type; and the invention proper concerns itself with noise reducing devices that include, or coact with, such rotary slide-valve devices.

The two mutually engaging surfaces of the rotary slide-valve device may have any suitable cooperating shape. For example, in Figs. 1 and 2 these surfaces are illustrated as being planar, at K. As mentioned, each cylinder port opens into the valve surface of the cylinder member and travels periodically over the slots in the fixed control face of the valve during rotation of the cylinder member so that a temporary communication is established between the slots and the ports. This will be more fully understood with reference to the machine exemplified by Figs. 1 and 2.

FIGS. 1 AND 2

The illustrated hydraulic multi-cylinder machine has a stationary housing A in which a slanting control body B is mounted. The housing is axially traversed by a shaft D on which a drum-shaped cylinder structure E is mounted. The cylinder drum E has a number of cylinders F formed by bores uniformly distributed about the shaft D and extending parallel to the shaft axis. Pistons G are reciprocable in the respective cylinder bores. Each cylinder bore has a port 5 which, in the proper rotational position of the cylinder bore, communicates with one of two control slots 1a or 1b in a planar valve surface K of the housing assembly. The slots 1a and 1b are connected with oil inlet and outlet lines respectively.

Assuming that the machine is operating as a pump, the shaft D is driven to rotate the cylinder structure E while the oil lines are under pressure. During rotation of the cylinder structure E, the pistons G, in gliding engagement with the control surface of member B, are periodically moved into and out of the cylinder bores F so as to form respective variable-volume chambers together with the cylinder structure. The piston G shown in lowermost position at the left side of the illustration moves upwardly and inducts oil through the inlet slot 1a and the port 5 until it almost reaches the uppermost position of the piston G shown at the outermost right of the cylinder drum. Thereafter the port 5 is connected with the outlet slot 1b, and the piston is forced back into the cylinder to deliver oil into the slot 1b, proper check valves being provided in the inlet and outlet lines as usual for such purposes.

It should be noted, however, that for the purpose of illustration, the valve member A' in Fig. 1 is shown 90° turned from its correct position. That is, the lowermost and uppermost position of each piston, that is the two dead-center positions, are actually located on the neutral

axis NA indicated by a vertical dot-and-dash center line in Fig. 2; and the two valve slots 1a and 1b lie symmetrical to that center line, also as shown in Fig. 2.

Fig. 2 also shows one of the two hydraulic lines L 5 that communicate with the valve slots 1a and 1b respectively and hence also with the individual ports 5 and cylinder chambers F then registering with the respective slots.

In hydraulic machines having a constant length of 10 piston stroke the control body B is fixed and may form part of the machine housing or be rigidly joined therewith. In machines having an adjustable piston stroke for control of delivery, the desired adjustability can be obtained, for example, by making the control body B adjustable as regards its angle of inclination. In the embodiment illustrated by way of example, the control body B is mounted on a calotte-shaped body P which can be angularly displaced in housing A by means of an arm Q. When arm Q is in central position, i.e. coaxially 15 aligned with the axis of shaft D, the control body lies horizontal, and the piston stroke is zero so that the hydraulic delivery during rotation of the cylinder drum is also zero. Arm Q can be shifted from the zero position to the right or left to set any desired piston stroke 20 length within the available range of positive and negative directions of delivery.

Now, according to the invention, each of the valve slots 1a, 1b has both of its ends in the direction of rotation 25 subdivided into a number of auxiliary slots such as those 30 denoted in Figs. 2 and 3 by 2a, 3a, 4a, and 2d, 3d, 4d for slot 1a, and by 2b, 3b, 4b, and 2c, 3c, 4c for slot 1b (Fig. 3). These partitioned-off slots, hereinafter called "auxiliary slots" are in communication with respective 35 ducts or lines such as those shown at 6a, 7a, 8a and 6d, 7d, 8d in Fig. 2, through which each auxiliary slot can communicate with the adjacent main slot 1a or 1b under control by a hydraulic, valve-type slot control 40 switch described below with reference to Fig. 3 and the other embodiments. It will be apparent that by virtue 45 of such a control device, the angular or arcuate length of the slots 1a and 1b in each quadrant of the valve control face or circle of machine rotation can be lengthened and shortened.

Before explaining this more in detail, it may be mentioned that relative to the invention still more fully to be 45 described, the particular machine design here used by way of example is not essential except for the basic feature, mainly the slots and parts, of the rotary slide valve and these may be incorporated into hydraulic 50 machines having cylinders mutually oriented in directions other than as specifically illustrated and described herein. The arrangement and structural design of the hydraulic circuitry is likewise not essential, the term "line" being used herein to denote a hydraulic circuit connection regardless of whether it is formed by bores, hollows or 55 ducts in the valve members or machine components themselves or whether pipes or other tubing are used.

FIG. 3

Of the above-described hydraulic machine, Fig. 3 60 shows schematically only the main slots 1a and 1b of the valve control face and the auxiliary slots 2a, 3a, 4a; 2b, 3b, 4b; 2c, 3c, 4c; and 2d, 3d, 4d. It is assumed, as an example, that the cylinder body (E in Fig. 1) cooperating 65 with the valve slots has seven cylinders. The seven cylinder ports 5 are indicated by dot-and-dash lines. The vertical center line NA-NA indicates the neutral axis.

The auxiliary slots 2a, 3a, and 4a are connected through 70 respective hydraulic lines, 6a, 7a, 8a with one of four switching devices of slide-valve type. The auxiliary slots 2b, 3b, 4b are connected with another one of the switching devices through hydraulic lines 6b, 7b, 8b. The auxiliary slots 2c, 3c, 4c are connected through lines 6c, 7c, 8c with the third device; and the slots 2d, 3d, 4d 75 are connected through lines 6d, 7d, 8d with the fourth

switching device. The four switching devices comprise respective cylinder sleeves 9a, 9b, 9c and 9d in which respective piston sliders 10a, 10b, 10c and 10d are displaceably guided and sealed for oil pressure. Aside from the above-mentioned hydraulic lines, two further lines 11a, 11b extend from control slot 1a to cylinder sleeves 9a and 9b respectively; and corresponding lines 11c, 11d connect control slot 1b with the respective sleeves 9c and 9d.

Each of the piston sliders 10a, 10b, 10c and 10d has a constricted portion 12a, 12b, 12c or 12d whose axial length is such as to embrace all port openings of the respective line groups such as 6a, 7a, 8a, 11a. During axial movement of the piston sliders, they are unilaterally loaded by respective pressure springs 13a, 13b, 13c and 13d. Each spring abuts against a set screw 14 secured in a threaded cap 15.

A further hydraulic line 16a connects the control slot 1a with the pressure spaces 17a and 17c of the two sleeves 9a and 9c, and with spring spaces of the two other sleeves 9b and 9d. Similarly, another line 16b connects control slot 1b with the pressure spaces 17b, 17d of sleeves 9b, 9d and with the spring spaces of sleeves 9a and 9c.

All hydraulic lines are illustrated in single-line fashion; hydraulic junctions between the lines are indicated by dots, the crossing of lines as such being understood not to involve a hydraulic connection.

The operation is as follows.

The illustrated position of the piston sliders corresponds to a pressure difference $p_2 - p_1 = \text{zero}$. The pressures p_2 and p_1 in respective control slots 1a, 1b may have any value up to the rated permissible maximum. According to definition of p_2 and p_1 (see above), p_2 is always equal to or larger than p_1 ; and the control slot of the control face possessing this pressure p_2 is hereinafter designated as the "pressure slot," whereas the control slot subjected to the pressure p_1 is called the "suction slot."

In the illustrated position of pressure balance ($p_2 = p_1$) the constrictions 12 (a to d) of the piston sliders connect all respective lines 6 (a-d), 7 (a-d), 8 (a-d), 11 (a-d) and hence all auxiliary slots 2, 3, 4 with the correlated control slots 1a or 1b. During CL-rotation of the cylinder ports 5, these ports travel once over both control slots during each full rotation and are thus alternately subjected to the pressures p_1 and p_2 . The pressures p_1 and p_2 , of course, are also identical with the operating pressure in the hydraulic connecting lines (L in Fig. 2) of the multi-cylinder machine itself, since these connecting lines (L) directly communicate with the respective control slots 1a, 1b.

For explanation, assume that the uppermost cylinder port 5 which in Fig. 3 is just travelling across the NA axis appertains to a cylinder whose displacer member (piston G in Fig. 1) is in V_{za} -position, i.e. in outer dead center, so that after further rotation of $\alpha = 180^\circ$ this particular cylinder will reach the V_{zd} -position, i.e. the inner dead-center point. With CL-rotation of the cylinder body (E in Fig. 1) and its cylinder ports 5, the foregoing assumption corresponds to a positive value of $+V_H$; and the hydraulic machine operates either as a pump of constant piston stroke in CL-rotation, or as a motor in ACL-rotation. Under both conditions, the pressure p_2 obtains in the control slot 1b so that this slot represents the pressure slot, while slot 1a is the suction slot.

The uppermost cylinder port 5 (Fig. 3) when passing across the NA axis has just left the last auxiliary slot 2a of the suction slot 1a. Hence the cylinder volume V_{za} is subjected to the pressure p_1 . The first auxiliary slot 2b of pressure slot 1b already possesses the full pressure p_2 . At pressure balance ($p_1 = p_2$) no pressure change takes place in the cylinder and therefore no noise is produced.

Disregarding for a moment the effect of the auxiliary

slots, it would appear that, as soon as the pump takes up hydraulic power so that p_2 becomes larger than p_1 , an almost sudden increase from p_1 up to p_2 would occur in the stroke space of the cylinder which would tend to produce noise dependent, among other things, upon the magnitude of the pressure difference. After rotation of $\alpha = 180^\circ$, a reverse equalization of the cylinder pressure from p_2 toward p_1 would occur just as suddenly as the cylinder port 5 commutes from auxiliary pressure slot 2c to auxiliary suction slot 2d. Each such sudden change in cylinder pressure varies the mechanical stresses imposed upon the mechanism and its housing thus exciting sound-producing oscillations.

However, in the device according to Fig. 3 such noisy performance is subdued or eliminated by virtue of the following effects. The pressure difference $p_2 - p_1$, acting through hydraulic lines 16a, 16b (pressure p_2 being effective in pressure slot 1b), causes a displacement of the piston sliders 10b, 10d toward respective springs 13b and 13d until the increasing spring force and the displacing force caused by p_1 are just balanced by the displacing force caused by p_2 . During this equalizing performance, for instance under increasing differential pressure $p_2 - p_1$, the piston sliders 10b and 10d sequentially disconnect the auxiliary slots 2b, 3b, 4b and 2d, 3d, 4d from the lines 11b, 11a and thus from main slots 1b and 1a respectively. Therefore each cylinder port 5, after passing across the neutral axis NA, encounters an increasing number of closed auxiliary slots of the group 2b, 3b, 4b. During the same angle of rotation, the reciprocating machine piston already reduces the cylinder volume V_{za} by an amount which increases with the angle of rotation, so that a pressure increase occurs in the cylinder chamber in accordance with the elasticity constants C_1, C_2 .

Analogously, the auxiliary slots 2d, 3d, 4d at main slot 1a, during the progressive shortening of the slot group commencing at 4d, cause an increase in cylinder volume V_{zd} due to the piston movement commencing at this moment. As a result, the cylinder chamber, now remaining closed, is subjected to a reduction in pressure in conjunction with the constants C_1, C_2 . In accordance with the law of motion of the machine pistons in dependence upon the angle of rotation α , that is the dependence of the displacement volume V_h upon the angle α , there is for each pressure drop $p = p_2 - p_1$ a definite angle α_k or α_e at which the pressure balance will obtain in each cylinder port 5 at the pressure p_2 or p_1 .

In accordance therewith, the springs 13 (a to d), if desired in conjunction with a suitable adjustment of the axial spacing between the port openings at which the hydraulic lines (for instance 6a, 7a, 8a, 11a) communicate with the interior of the switch-valve sleeve (9a), are so adjusted by means of the set screws 14 that the displacement of the piston sliders caused by the difference pressure $p_2 - p_1$ always automatically regulates the compression or expansion by correspondingly adding and disconnecting the auxiliary slots as required for the desired pressure equalization. This automatic regulation occurs with an accuracy which increases with the number of the auxiliary slots provided.

During the operating condition just described, the pressures p_1, p_2 also act upon the piston sliders 10a, 10c. However, the pressure p_2 is active in the spring spaces 13a, 13c and the pressure p_1 in the pressure spaces 17a, 17c so that the piston sliders 10a, 10c retain the illustrated positions. Consequently, the slots 2a, 3a, 4a remain fully in hydraulic connection with the control slot 1a; and the slots 2c, 3c, 4c remain fully connected with control slot 1b. As a result, the suction slot 1a, for instance, can fill the cylinder chambers (F in Fig. 1) through the ports 5 until the respective ports travel over the neutral axis NA, that is until the pistons (G in Fig. 1) reach the effective outer dead-center point. Analogously, the variable-volume cylinder chambers are in hydraulic connection with the pressure slot at the end

of the pressure stroke and until the pistons reach the effective inner dead-center point.

In this manner, the noise reducing device satisfies the condition that the compression angle α_k and the expansion angle α_e , when the machine is operating as a pump, must always be located entirely behind the neutral axis seen in the direction of rotation. Since the displacement of the piston sliders 12 (a to d, Fig. 3) accurately follows the gradual variation in pressure difference, the closing of the individual control ports in the switching sleeves 9a to 9d of the slot switching devices likewise takes place gradually. Therefore the adding and disconnecting of the individual auxiliary slots takes place with a variable throttling effect. This smoothens in favorable sense the incremental regulation of α_k and α_e stemming from the limited number of the auxiliary slots. With the exception of the throttling component, the described pressure adaptation takes place without losses. This is so because the work done by the drive during the compression occurring when the variable-volume cylinder space is temporarily closed, is regained by the expansion occurring at the beginning of the suction stroke.

During operation in practice certain operating conditions may occur which cause a reversal in power flow. For example, when in a hydraulic drive comprising a pump and a motor, the hydraulic motor occasionally is subjected to over-hauling load and runs ahead of the pump, the motor temporarily acts reversely as a pump and now drives the pump proper in the original direction of rotation as a motor. Under such conditions, the valve slot normally operating as a suction slot in the control face of the pump, now receives the higher pressure and, in accordance with the definitions of the present specification, must now be considered as the pressure slot, whereas the previous pressure slot becomes the suction slot. The CL-sense of rotation presumed in the foregoing considerations remains unchanged during such power reversal. When now p_2 changes over from control slot 1b to control slot 1a, then the piston sliders 10b and 10d (Fig. 3) remain in the illustrated starting positions, whereas the piston sliders 10a and 10c now connect and disconnect the two groups of auxiliary slots 2a, 3a, 4a and 2c, 3c, 4c in dependence upon the pressure difference $p_2 - p_1$, so that again the angles α_k and α_e are continuously and automatically regulated as required for pressure adaptation. During this operation the cylinder ports 5 are disconnected, or may be disconnected from the control slot 1b, now acting as suction slot, already before the ports 5 reach the inner dead-center point. Analogously, the ports 5 may now be disconnected from slot 1a, now acting as the pressure slot, before the outer dead-center point is reached. At the same time, the auxiliary slots at the other slot end of slots 1b and 1a remain in full communication with the appertaining main slot.

Consequently during such operating conditions the requirements above explained are again satisfied. That is, when operating the machine as a motor, the compression angle α_k and the expansion angle α_e always have their full magnitude located ahead of the neutral axis; and the regulation again takes place automatically and without appreciable losses because the compression work done prior to passing through the neutral axis is regained by the expansion work done subsequent to passage through neutral.

If the machine above considered is being operated, with constant stroke and constant sign of V_H , as a pump in ACL-rotation, then all regulating conditions remain as last described except that the delivering direction is reversed, and the entire extent of the angles α_k and α_e again lies ahead of the neutral axis.

With this ACL-direction of rotation, too, there may occur the case that the power flow reverses itself so that the pump must run as a motor. Under these conditions, the pressures p_1 and p_2 change their respective slots as

already described. Control slot 1a being now the suction slot and slot 1b the pressure slot. As a result, and as will be recognized from the diagram of Fig. 3, the piston sliders 10a, 10c again shift into the illustrated starting positions, and the piston sliders 10b, 10d take care of regulating the two respective groups of auxiliary slots 2b, 3b, 4b and 2d, 3d, 4d. This causes the desired expansion in the individual cylinder chambers to occur in the range of slots 2b, 3b, 4b; and analogously results in the desired compression at slots 2d, 3d, 4d.

In summary, a hydraulic machine equipped with a noise reducing device according to Figs. 1, 2 and 3 can be operated satisfactorily in both directions of rotation as a motor as well as a pump. The angles α_k and α_e regulate themselves automatically in the desired sense as to magnitude and sign.

Referring to the above-mentioned table, the types of machine operation described in the foregoing with reference to Fig. 3 correspond to those denoted in the table by Ia, Ib, IIIa, IIIb. In all these cases the magnitude V_H has a positive sign.

When the drive of the displacement members, i.e. the machine pistons, is phase displaced 180° relative to the slide valve control, then this change corresponds to an exchange of the inner and outer dead-center positions and hence to an exchange of V_{z1} and V_{z2} as regards their above-assumed respective locations relative to the rotation at the valve control face; and the direction of delivery is reversed under all operating conditions so far considered in the foregoing. The piston machine can then be run satisfactorily under all operating conditions with a negative sign of V_H listed in the table as IIa, IIb and IVa, IVb. These operations merely require connecting the hydraulic line 16a with the control slot 1b, and line 16b with the slot 1a. This can be done by means of other hydraulic lines or by additional switching valves such as those described further below.

The noise reducing performance of the device described above comes about by virtue of the fact that the increase and decrease of pressure in the individual cylinder chambers is caused to take place over a definitely given angle of rotation of the machine independently of the speed of rotation, the period of time for passing through this angle and hence available for pressure equalization being considerably longer than with slide valve controls not equipped with this device. Furthermore, in the described device the angle of rotation regulates itself automatically in a favorable manner so that with an increasing difference pressure $p = p_2 - p_1$ there is also available an increasing angle of rotation for effecting the pressure equalization. The improved noise reduction is therefore secured under all operating conditions.

In Fig. 3 the elastic means are shown as simple pressure springs 13 (a to d). In order to adapt the regulating operation of the piston sliders to the particular requirements of the given machine performance, different possibilities in the design of the progressive angle of pitch of the turns of these springs or in the number of springs per set will occur to one skilled in the art upon reading this disclosure, for securing other desired spring-force characteristics of the springs 13a, 13b, 13c, 13d.

FIG. 4

In the embodiment illustrated in Fig. 4, the control slots 1a, 1b and the appertaining groups of auxiliary slots are exactly the same, with respect to design and position relative to the neutral axis, as described above with reference to Fig. 3. In contrast to Fig. 3, however, the four actuator members or piston sliders 10a, 10b, 10c, 10d are combined to form two double-acting piston sliders 19e and 19f. The two piston sliders are guided and oil-sealed in respective switching sleeves 20e and 20f and are each provided with two constrictions 21a, 21b and 21c, 21d which correspond to the constrictions denoted by 12a, 12b, 12c and 12d in Fig. 3.

The control slot 1a (Fig. 4) is connected by oil lines 1a, 11d with the sleeve spaces in which the constrictions 1a and 21d of the piston sliders are located. Control slot 1b is similarly connected through lines 11b, 11c with the sleeve spaces for constrictions 21b, 21c. The hydraulic connections between the respective control slots of the valve and the above-mentioned sleeve spaces are continuously open. The control slot 1a is further continuously connected through hydraulic line 11a, the constriction 21a and a connecting line 23e with the pressure space 22a in which the spring 13b is located; and control slot 1a is connected through line 11d, constriction 21d and line 23f with the pressure space 22c in which the spring 13d is located. The control slot 1b, analogously, is in continuous hydraulic connection through line 11b, constriction 21b and a line 24e with the pressure space 22b of spring 13a; and control slot 1b is continuously connected through lines 11c, construction 21c and a connecting line 24f with the pressure space 22d of spring 13c. The illustrated position of the piston sliders corresponds to an operating condition in which $p_2 = p_1$.

For explaining the operation of the device it may again be presumed that the cylinder port 5 just located above the neutral axis NA appertains to a cylinder chamber V_{za} condition, that is, the machine piston in this cylinder chamber is just in outer dead-center position. Also assume that the stroke volume of the machine is constant. The control and regulating phenomena are in accordance with those explained with reference to the embodiment of Fig. 3, as will be recognized from the most important operations presently described with reference to the types of operation listed in the above-presented table.

(1) *Operation type Ia.*—Control slot 1b is the pressure slot subjected to pressure p_2 . Control slot 1a is the suction slot subjected to pressure p_1 . The slider 19e is loaded from spring space 22b by the pressure p_2 , and from spring space 22a by the pressure p_1 acting upon the slider in opposition to pressure p_2 . Consequently, the piston slider 19e is displaced toward the right until the force of spring 13b balances the hydraulic difference force. Now the middle portion of the piston slider 19e is effective, in dependence upon the pressure difference $p_2 - p_1$, to connect a certain number of auxiliary slots of the series 2b, 3b, 4b. The connected number of auxiliary slots is dependent upon the spring characteristic and the axial spacing between the port openings of lines 6b, 7b, 8b at switching sleeve 20e. As a result, the cylinder ports 5, during CL-rotation, must pass through a certain angle of rotation, namely the compression angle α_k commencing from the neutral axis NA, until the ports enter in communication with one of the open pressure slots or with the main pressure slot 1b itself. At the moment when such hydraulic connection is established, hereinafter briefly called "critical moment," the cylinder pressure p_z is approximately or accurately equal to p_2 . The piston slider 19e simultaneously controls the neighboring auxiliary slots of the suction slot 1a and, in the present case, completely opens these auxiliary slots so that they are all in communication with the suction slot 1a.

The slider 19f is loaded from spring space 22d by the pressure p_2 and from spring space 22c by the opposed pressure p_1 . Consequently, the piston slider 19f moves toward the left until the force of spring 13d balances the hydraulic difference force. This causes the middle portion of piston slider 19f to close a certain number of auxiliary slots of the series 2d, 3d, 4d, this number being dependent upon the magnitude of the pressure difference $p_2 - p_1$, the spring characteristic and the axial spacing of the openings of lines 2d, 3d, 4d in switching sleeve 20f. As a result, the cylinder port 5, during CL-rotation, must pass beyond the neutral axis NA through a certain angle of rotation, namely the expansion angle α_e until the ports enter into communication with one of the open auxiliary slots or with the main suction slot 1a itself.

cation with one of the open auxiliary slots or with the main suction slot 1a itself. At the critical moment when such communication becomes established, the cylinder pressure p_z is approximately or accurately equal to the pressure p_1 . The piston slider 19f simultaneously controls the neighboring auxiliary slots of the pressure slot 1b and, in the present case, completely opens these auxiliary slots so that they are all in hydraulic communication with the pressure slot 1b. The machine operates as a pump with a positive value of V_H , and the angles α_k and α_e , seen in the direction of rotation, are fully located behind the neutral axis NA.

(2) *Operation type IIIa.*—Control slot 1a is the pressure slot. Slot 1b is the suction slot. The piston slider 19e, following the pressure difference $p_2 - p_1$, is displaced toward the left; and slider 19f is displaced toward the right. The auxiliary slots 2b, 3b, 4b of suction slot 1b and the auxiliary slots 2d, 3d, 4d of the pressure slot 1a are completely opened, whereas the auxiliary slots 2a, 3a, 4a of pressure slot 1a and the auxiliary slots 2c, 3c, 4c of suction slot 1b are closed in accordance with the particular compression or expansion angle required for V_{za} and V_{zb} respectively. The piston machine operates as a pump with a positive value of V_H ; and the angles α_k and α_e , seen in the direction of rotation, are entirely located behind the neutral axis NA.

(3) *Operation type Ib.*—In this condition, slot 1b is the pressure slot and 1a is the suction slot. In accordance with the pressure difference $p_2 - p_1$ the piston slider 19e moves toward the right, and the slider 19f moves toward the left. The auxiliary slots 2a, 3a, 4a of suction slot 1a and the auxiliary slots 2c, 3c, 4c of pressure slot 1b are completely open, whereas the auxiliary slots 2b, 3b, 4b of the pressure slot and the auxiliary slots 2d, 3d, 4d of the suction slot are closed in accordance with the expansion and compression angles required for V_{za} and V_{zb} respectively. The machine operates as a motor with a positive V_H value; and the angles α_k and α_e , seen in the direction of rotation, have their full extent located ahead of the neutral axis NA.

(4) *Operation type IIIb.*—In this operation, control slot 1a is the pressure slot and 1b the suction slot. Under the pressure difference $p_2 - p_1$ the piston slider 19e is displaced toward the left and the piston slider 19f toward the right. The auxiliary slots 2b, 3b, 4b of suction slot 1b and the auxiliary slots 2d, 3d, 4d of the pressure slot 1a are completely opened. The auxiliary slots 2a, 3a, 4a of the pressure slot 1a and the auxiliary slots 2c, 3c, 4c are closed in accordance with the expansion and compression angles required for V_{za} and V_{zb} respectively. The machine operates as a motor with a positive V_H value; and the angles α_k and α_e , seen in the direction of rotation, are entirely located ahead of the neutral axis NA.

It will be recognized that in a device for noise reduction according to Fig. 4, all operating conditions characterized by a positive sign of V_H (displacement volume of machine piston at full stroke) satisfy all requirements. For operation under conditions involving a negative sign of V_H , the hydraulic lines 23e and 24e would have to be exchanged with the lines 23f and 24f. This can be done when installing the machine, or change-over switching valves may be used for this purpose as will be described in a later place.

FIG. 6

In the embodiment illustrated in Fig. 5, the control slots 1a and 1b and the appertaining auxiliary slots correspond, as regards arrangement and functioning, to those described above with reference to Figs. 2 to 4. Similar to the embodiment of Fig. 4, the device is provided with two double-acting piston sliders 25e, 25f which are displaceably guided in respective switching sleeves 26e and 26f. However, whereas in the embodiment of Fig. 4 each double-acting piston controls auxiliary slots of both main

control slots, each of the two sliders $25e$ and $25f$ in the device of Fig. 5 controls both groups of auxiliary slots appertaining to only one of the two respective control slots. For this purpose, the lines $2a$, $3a$, $4a$ and $2d$, $3d$, $4d$ of the auxiliary slots adjacent to the left control slot $1a$ lead to the switching sleeve $26e$; and the lines $6b$, $7b$, $8b$ and $6c$, $7c$, $8c$ lead to the switching sleeve $26f$. The piston slider $25e$ has a single constriction $27e$ continuously in hydraulic connection with the control slot $1a$ through a line $28e$. Similarly, the corresponding constriction $27f$ of piston slider $25f$ is continuously in hydraulic connection with control slot $1b$ through a line $28f$. In the illustrated center position, the constriction $27e$ extends along all openings, located axially beside one another, of the connecting oil lines of groups $6a$, $7a$, $8a$ and $6d$, $7d$, $8d$ as well as the opening of the line $28e$. Analogously, the constriction $27f$ embraces all openings, located axially beside one another, of the connecting lines $6b$, $7b$, $8b$ and $6c$, $7c$, $8c$ as well as the opening of line $28f$. The piston slider $25e$ is subjected to spring force in both directions of displacement due to the action of springs $13a$ and $13d$. Analogously, the piston slider $25f$ is under the force of opposingly acting springs $13b$ and $13c$. The spring spaces, namely the pressure spaces $22a$ and $22c$, are in continuous hydraulic connection with the control slot $1a$ through a line $29e$, the constriction $27e$ and the line $28e$. The pressure spaces for springs $22b$ and $22d$ are hydraulically connected through a line $29f$ with the sleeve space of constriction $27f$, and thence through a line $28f$ with the control slot $1b$. The coaction of the pressures p_2 and p_1 with the springs $13a$, $13b$, $13c$, $13d$ corresponds exactly to that described above with reference to Figs. 3 and 4. The operation of the machine during the various types of operation listed in the foregoing table is as follows:

(1) *Operation type Ia.*—In this condition, slot $1b$ is the pressure slot and $1a$ the suction slot. Under the pressure difference p_2-p_1 the piston slider $25e$ moves up, and the piston slider $25f$ moves down. The auxiliary slots $2a$, $3a$, $4a$ of the suction slot $1a$ and the auxiliary slots $2c$, $3c$, $4c$ of the pressure slot $1b$ are completely released, whereas the auxiliary slots $2b$, $3b$, $4b$ of the pressure slot, as well as the auxiliary slots $2d$, $3d$, $4d$ of the suction slot, are disconnected in accordance with the compression and expansion angles required for V_{za} and V_{zi} respectively. The machine operates as a pump with positive V_H ; and the angles α_k and α_e , seen in the direction of rotation, are entirely located behind the neutral axis NA.

(2) *Operation type IIIa.*—In this condition the control slot $1a$ is the pressure slot, and $1b$ is the suction slot. Under the pressure difference p_2-p_1 , the piston slider $25e$ moves down, and piston slider $25f$ moves up. The auxiliary slots $2b$, $3b$, $4b$ of suction slot $1b$ and auxiliary slots $2d$, $3d$, $4d$ of pressure slot $1a$ are completely opened. Auxiliary slots $2a$, $3a$, $4a$ of pressure slot $1a$ and auxiliary slots $2c$, $3c$, $4c$ of suction slot $1b$ are closed in accordance with the compression and expansion angle required for V_{za} and V_{zi} respectively. The machine operates as a pump with positive V_H value; and the angles α_k and α_e , seen in the direction of rotation, have their full extent located behind the neutral axis NA.

(3) *Operation type Ib.*—Control slot $1b$ is the pressure slot, and $1a$ is the suction slot. Under the pressure difference p_2-p_1 , the piston slider $25e$ moves up, and slider $25f$ moves down. The auxiliary slots $2a$, $3a$, $4a$ of suction slot $1a$ and auxiliary slots $2c$, $3c$, $4c$ of pressure slot $1b$ are completely released, whereas the auxiliary slots $2b$, $3b$, $4b$ of the pressure slot and the auxiliary slots $2d$, $3d$, $4d$ of the suction slot are disconnected in accordance with the expansion or compression angle required for V_{za} or V_{zi} . The machine operates as a motor with a positive V_H value; and the angles α_k and α_e , seen in the direction of rotation, have their full extent located ahead of the neutral axis NA.

(4) *Operation type IIIb.*—In this condition, control

slot $1a$ is the pressure slot, and $1b$ is the suction slot. Under the pressure difference p_2-p_1 , the piston slider $25e$ moves down, and slider $25f$ moves up. The auxiliary slots $2d$, $3d$, $4d$ of the pressure slot $1a$ are completely released, whereas the auxiliary slots $2a$, $3a$, $4a$ of the pressure slot $1a$ and the auxiliary slots $2c$, $3c$, $4c$ of the suction slot are closed in accordance with the expansion and compression angles required for V_{za} and V_{zi} respectively. The machine operates as a motor with positive V_H value; and the angles α_k and α_e are located ahead of the neutral axis NA seen in the direction of rotation.

In this embodiment of Fig. 5 the springs $13a$, $13b$ must be adapted, as is the case in the embodiments of Figs. 3 and 4, to the condition $(V_H/V_{H\max.}, V_{za})$ required for V_{za} . Analogously, the springs $13c$ and $13d$ must be adapted in accordance with the condition $(V_H/V_{H\max.}, V_{zi})$ applying to V_{zi} .

As shown in the foregoing, a noise reducing device according to Fig. 5 has the effect that the piston engine satisfactorily runs with optimum noise reduction during all operating conditions involving a positive sign of V_H . If the same machine is to be operated under conditions involving a negative sign of V_H , it would be necessary to connect the line $29e$ with the control slot $1b$ and the line $29f$ with the control slot $1a$. This can be done when installing the machine or by means of a change-over switching valve as described further below.

FIG. 6

30 In the modified embodiment illustrated in Fig. 4, the two control slots $1a$ and $1b$ with the groups of auxiliary slots $2a$, $3a$, $4a$, $2d$, $3d$, $4d$, and $2b$, $3b$, $4b$, $2c$, $3c$, $4c$ cooperate with a switching-valve sleeve $20e$ provided with a double-acting piston slider $19e$, valve springs $13a$ and $13b$, and hydraulic lines $23e$ and $24e$. The design and 35 functioning of these components is similar to the components denoted in Fig. 4 by the same respective reference characters. However, in contrast to the embodiment of Fig. 4, the one shown in Fig. 6 lacks the second 40 switching sleeve $20f$ with lines $23f$, $24f$ and connecting lines $2c$, $3c$, $4c$, $11c$, $2d$, $3d$, $4d$ and $11d$. In lieu thereof, the device is provided with connecting ducts or lines $2ac$, $3ac$, $4ac$ which connect the auxiliary slots $2a$, $3a$, $4a$ with respective slots $2c$, $3c$, $4c$. Similar ducts or lines $2bd$, $3bd$, $4bd$ connect the auxiliary slots $2b$, $3b$, $4b$ with the 45 respective slots $2d$, $3d$ and $4d$. The interconnections are continuously open hydraulically.

A prerequisite for the proper functioning of this device is an odd number of machine cylinders and hence a correspondingly odd number of cylinder ports 5 , whereby 50 the formation of undesired short circuit connections between two variable-volume cylinder chambers through the last-mentioned connecting ducts or lines is prevented.

The performance of a device according to Fig. 6 is 55 exactly in accordance with the one described with reference to Fig. 4 and for that reason need not be further discussed. Such a noise reducing device is relatively simple and cheap, although it has the disadvantage, compared with devices according to Figs. 3 to 5, that during the automatic regulation of α_k and α_e only the median 60 values of both controlling magnitudes V_{za} and V_{zi} are taken into account. However, the illustrated device is favorably applicable in such cases where, by virtue of a suitable design of the multi-piston machine—for instance by giving the auxiliary slots $2c$, $3c$, $4c$ and $2d$, $3d$, $4d$ a slight tangential width or small angular extent—care 65 has been taken that, with constant-stroke operation of the machine, each angle α_k or α_e , regulated at the auxiliary slots $2a$, $3a$, $4a$ or $2b$, $3b$, $4b$ in dependence upon the pressure difference p_2-p_1 by the piston slider $19e$ and the switching sleeve $20e$, has a value of satisfactory approximation.

FIG. 7

The noise reducing devices so far described comprise 70 a particularly designed control apparatus for distributing

the liquid operating medium onto the individual cylinder chambers in synchronism with the piston reciprocation, and this distributor apparatus cooperates with a switching-valve device to automatically regulate the angle α_k and α_e most favorable for noise reduction. However, further system components are required to make devices of this kind suitable for use with hydraulic machines whose piston-stroke volume V_H , or the delivering direction i.e. the sign of V_H , or both, are variable.

Fig. 7, therefore, exemplifies a complete noise reducing control system which automatically affords optimum noise reduction for all types of operation listed in the foregoing table. The main control valve MCV for the liquid pressure medium and also the slot-controlling switching valves SCS comprising two double-acting piston sliders correspond to the embodiment illustrated in Fig. 4. For that reason, the individual components are given the same reference characters as in Fig. 4 to the extent necessary for explaining and understanding the system. A difference of the just-mentioned components in the system of Fig. 7, as compared with the noise reducing device shown in Fig. 4, relates to the springs 13a, 13b, 13c, 13d acting upon the piston sliders. While in the embodiment of Fig. 4 the two springs correlated to one end of the control slots are adapted to a constant value of V_{za} and the other two springs are adapted to a constant value of V_{z1} , all four springs for the piston sliders 19e and 19f in Fig. 7 are uniformly rated. The rating of the springs is such that, in conjunction with the piston sliders and the axial spacing of the port openings for hydraulic lines 6a, 7a, 8a, 6b, 7b, 8b, 6c, 7c, 8c and 6d, 7d, 8d, a regulation of the angles α_k and α_e is brought about for the condition $V_{z1}=V_{za}=V_z$.

In order to obtain automatic regulation of the angles α_k and α_e , two separate pressure regulators PRL and PRR are provided for the V_{z1} -side and the V_{za} -side of the valve control face respectively. The two pressure regulators are supplied with the pressure difference $p_2-p_1=p$, and they convert this pressure difference into a pressure p_a or p_1 in dependence upon the variables:

$$V_{z1}=f(V_z, V_H/V_{H\max.})$$

or

$$V_{za}=f(V_z, V_H/V_{H\max.})$$

and

$$\alpha_1=f(V_H, V_H/V_{H\max.})$$

or

$$\alpha_a=f(V_H, V_H/V_{H\max.}), C_1, C_2$$

The converted pressures p_a and p_1 are supplied to the slot-control switching devices SCS at the V_{z1} -side and V_{za} -side respectively, so that the value of the angle α_k or α_e is produced in the respective switching devices SCS as a function of all variables involved.

The pressure regulators PRL, PRR are designed as proportional regulators. That is, they always vary the pressure p , irrespective of its absolute magnitude, in a given ratio which, however, may be set to a proper value from the operation controls of the hydraulic machine. Each of the two regulators comprises two control cylinders or bores 30, 31 in which respective controls 32 and 33 are slidable. The two pistons in each regulator abut against the respective arms of a teeter lever 34 to produce mutually opposed torques. Each teeter 34 is mounted on a swing arm 35 linked to the regulator housing 36. The control bores 30 and 31 are closed at the top. The pressure $p=p_2-p_1$ to be converted is continuously supplied to the control bores 30 through a line 37a or 37b and pushes the control pistons 32 against the respective teeters 34.

In the illustrated normal operating condition, the upper end of each control piston 32 uncovers a lateral port opening of control bore 30, whereby the pressure p is also applied through a line 38 to the interior of the control bore 31 where it imposes a corresponding load upon the control piston 33. When the torque imposed upon the

teeter 34 by piston 33 is greater than that produced by piston 32, the piston 33 moves down and the teeter forces the piston 32 up. Then the control piston 32 covers the port of line 38 and thus terminates the equalizing performance. The pressures in the respective control bores 30 and 31 are then related to each other in inverse proportion to the products formed by the cross-sectional area of the control pistons times the instantaneous leverage arm effective at the teeter 34. Consequently the line 39 connected to the end of the control bore is at any time subjected to a pressure whose relation to the pressure p acting in the control bore corresponds to a ratio inverse to that of the instantaneously active leverage arms of the teeter 34.

15 The control bore 31, too, is provided with a lateral port from which a line 40 leads to a space of negligible or zero pressure, for instance into the housing 36 of the regulator which is under ambient atmospheric pressure. The port of line 40 is uncovered by control piston 33 20 during its downward motion at a moment when this piston has already shut off the supply to line 38. Thus the line 40 permits the occurrence of a pressure drop in control bore 31 and line 39.

During operation the following regulating play takes 25 place: Pressure p from line 37a or 37b forces the control piston 32 in Fig. 7 downward. Control piston 32 then uncovers the port of line 38 so that the pressure in control bore 31 increases. This pressure forces the regulator piston 33 downward under the condition that the 30 torque thereby imposed upon teeter 34, in accordance with the piston area and a suitable leverage ratio, can never be smaller than the torque produced by the control piston 32. The teeter 34, now moving counterclockwise, forces the piston 32 upward so that this piston covers the 35 port of line 38 and thus discontinues the supply of pressure to the control bore 31. The torques produced by both pistons are then in equilibrium.

When the pressure p in line 37a or 37b increases, the 40 regulating play repeats itself until a new balance condition is reached. When the pressure p in line 37a or 37b drops, the pressure in line 39 above regulator piston 33 preponderates, and piston 33 moves downward until it uncovers the port of line 40 thus permitting the pressure medium to escape. As soon as the pressure in control bore 31 and line 39 again corresponds to the instantaneous balance condition at the teeter 34, the regulator piston 33 again rises and terminates the escape of medium through line 40. If the two pistons 32, 33 in each regulator have the same diameter, the regulated pressure ratio always corresponds to the effective leverage ratio 50 of the teeter 34.

It is possible to combine the individual variables into a single variable related to the ratio $V_H/V_{H\max.}$, and to use this totalized variable for controlling the pressure ratio p/p_1 or p/p_a to be regulated by the pressure regulators PRL and PRR. The pressure p_1 or p_a is supplied to the slot-control switching devices SCS for the proper V_{z1} -side or V_{za} -side of the rotary control valve MCV, where this pressure imposes a load upon one end of the piston slider, while the other end of the same slider is in communication with a space of negligible pressure through control means still to be described. In the system of Fig. 7 the required dependence of the totalized variable upon the ratio $V_H/V_{H\max.}$ is secured by controlling the pivot positions of the respective teeters 34, 55 and thus the effective teeter leverage ratio in the two pressure regulators PRL and PRR, in dependence upon the selected setting of the piston-stroke adjusting device of the multi-cylinder engine. For this purpose the stroke-setting control means of the machine, such as the control 60 arm Q in Fig. 1, are connected by a linking rod (41' in Fig. 1) or other suitable transmission with a lever 41 pivotally mounted in the housing 36 of the pressure regulators. The connection is such that the lever 41 occupies the illustrated mid-position when the piston stroke 65

of the machine is set to zero, and that the lever 41 is turned in one or the other direction to the dot-and-dash positions when the stroke length is increased from zero toward an increasing value of $V_H/V_{H\max}$, the direction of lever displacement being dependent upon the delivering direction, i.e. the sign of V_H .

A cam member 42 with two symmetrical cam faces is rigidly connected with lever 41 within the regulator housing 36. Cam member 42 is engaged by two cam rollers 45a and 45b journalled on respective swing arms 43 which are pivotally linked to the housing 36. Each of swing arms 43 is linked with one of the swing arms 35 by a linking rod 44 so as to form a linkage parallelogram. When the control lever 41 together with cam member 42 are moved about their common pivot, the linkage parallelogram in each regulator varies the leverage ratio at teeter 34 depending upon the cam contour of member 42. When the cam rollers 45a, 45b occupy the respective innermost positions shown in Fig. 7, the torques produced by the two regulator pistons 32 and 33 under the same pressure in the two control bores 30, 31 are equal or, preferably, the torque of piston 33 is slightly preponderant. This means, that with lever 41 in the illustrated mid-position, the pressure $p_a = p_1$ regulated by the pressure regulators in the lines 39 is nearly or exactly equal to the difference pressure $p = p_2 - p_1$ supplied through the line 37a or 37b. When the lever 41 is turned away from its normal position, the cam member 42, by virtue of its particular cam contours, is effective to always produce a change in the leverage ratio of the teeters dependent upon the above-mentioned totalized variable, thus also securing a corresponding change in the pressure being regulated.

The above-mentioned totalized variable for the V_{z1} -side (neutral zone of the valve control face corresponding to the smaller cylinder volume) of the rotary side valve differs in value from the totalized variable applying to the V_{z2} -side (the other neutral zone corresponding to the larger cylinder volume). In accordance therewith, the cam member 42 possesses for each roller 45a, 45b two different cam portions of different curvature merging at the zero position. For example, when the control lever 41 is turned into the $+V_H$ -range, shown at the left of lever 41 in Fig. 7, the left-hand pressure regulator PRL regulates the pressure p_a required on the V_{z2} -side for automatic regulation of the angle α_k or α_e ; whereas the right-hand pressure regulator PRR regulates the pressure p_1 required for the automatic regulation of the angle α_k or α_e on the V_{z1} -side of the valve control face. When the control lever 41 is turned from zero position into the $-V_H$ -range, which corresponds to a different delivering direction of the machine operating as a pump, the pressure regulator PRL regulates the pressure p_1 and regulator PRR the pressure p_a .

When the piston machine is operating under a pressure p_1 of appreciable magnitude, this pressure may have an influence upon the true magnitude of p ; and such influence, for the reasons already mentioned, must be taken into account if exact performance of the noise reducing system is to be secured. For this purpose, the lines 46a and 46b extending from respective control slots 1a and 1b are led to a differential pressure regulator DPR which comprises a middle cylinder 47 coaxially joined on both sides with side cylinders 48a, 48b of smaller diameter. The differential regulator is provided with a stepped piston whose diametrically larger middle portion 49 is slideable and oil-sealed in the middle cylinder 47, and whose two lateral piston members 50 are similarly slideable in the side cylinders 48a and 48b respectively.

The stepped piston is axially movable to a limited extent sufficient for controlling the ports of two outlet lines 52a and 52b, these ports being located in the middle cylinder 47 close to the respective front sides of the middle piston 49 when the piston is in the illustrated mid-position. The outlet lines 52a and 52b are connected

through a common line 52 with a space of lower pressure, for instance and as shown, with the interior of the regulator housing 36. Each displacement of the differential piston from the neutral mid-position causes closing of one of the two outlet lines 52a, 52b respectively. Hydraulic connecting lines 53a and 53b open into the respective side cylinders 48a, 48b and are also in communication with the respective axial ends of the middle cylinder 47 so that each of lines 53a or 53b continuously connects one of the respective side cylinders with the one middle-cylinder space remote from that particular side cylinder. The port openings of lines 53a and 53b in the two side cylinders are so located as to become uncovered by the respective side pistons as soon as the middle piston 49, when moving axially, covers the port opening of the one outlet line 52a or 52b connected with the line 53a or 53b just closed.

The performance of the differential pressure regulator is in accordance with the following equation (Eq.):

$$F_a \cdot p_2 + F_b \cdot p_x = F_a \cdot p_1 + F_b \cdot p_y$$

or

$$F_a/F_b(p_2 - p_1) = p_y - p_x$$

wherein

25 p_1 and p_2 =pressure of control slots 1a, 1b in atmospheres of absolute pressure (ata.);

p_x =pressure of the outlet line 52 in ata.;

p_y =derived differential pressure, proportional to the pressure difference $p_2 - p_1$, in ata.;

30 F_a =cross-section area of the lateral piston portions 50;

F_b =cross-sectional area of the piston middle portion 49 minus the area F_a .

The operation of the differential pressure regulator is as follows:

35 For explanation the pressure p_x may be assumed to be 1 ata. (i.e. the equal to ambient atmospheric pressure). One side piston 50 is always loaded by the pressure p_1 , the other side piston by the pressure p_2 . Hence the stepped differential piston is subject to axial displacement under a force equal to the product $F_a(p_2 - p_1)$.

40 For instance, if p_2 is effective in side cylinder 48a, then the differential piston of device DPR moves toward the right and first closes the outlet line 52b. This already causes a pressure increase in the annular cylinder space at the right of the middle piston 49 because the oil content in the annular space, previously under little or no pressure because of the outlet line 52b, is now subjected to pressure by the annular portion of piston 49. The displacement of the differential piston toward the right continues as long as the product of the pressure p_y in the annular space at the right of the middle cylinder times the area F_b remains smaller than the product $F_a(p_2 - p_1)$. Ultimately the left side piston 50 uncovers the port opening of line 52a. Now the working medium, 55 under the pressure p_2 , passes from the side cylinder 48a into the line 53a until the pressure in line 53a, and thereby also in the communicating annular space of the middle cylinder 47, has risen to the static equilibrium of the differential piston. As soon as pressure p_y in line 53a

60 continues to increase (because p_2 is always greater than p_y), the forces which load the differential piston toward the left become preponderant and the differential piston is again shifted toward the left so that the side piston 50 again covers the port opening of line 53a. Now the pressure p_y in line 53a has the magnitude corresponding to the foregoing equation (Eq.), whereas the line 53b is without pressure because it now communicates with the escape line 52. As a result, the differential pressure regulator DPR has set itself in accordance with the instantaneously existing values of p_2 and p_1 , thus producing the desired differential pressure p_y .

If now, during the further operation of the multi-piston engine, the pressure p_2 increases or the pressure p_1 decreases, or if both events occur simultaneously, then the

above-described regulating performance repeats itself until a new balance condition is obtained. However, if the pressure p_2 decreases, or if p_1 decreases, or if both events occur, then the forces loading the differential piston toward the left become preponderant; and the piston, now shifting toward the left, uncovers the outlet line 52b until the pressure p_y in line 53a has declined in accordance with the new datum value.

It will be remembered that the above-described performance of a system according to Fig. 7 relates to operating conditions of the multi-cylinder machine under which the valve control slot 1a has the pressure p_2 and slot 1b has the pressure p_1 . It will be readily understood from the foregoing that when these conditions are reversed, that is, when slot 1a has the pressure p_1 and slot 1b the pressure p_2 , so that the differential pressure regulator DPR is loaded through lines 46a and 46b in the inverse relation, the regulating phenomena remain exactly as described above, with the only exception that then the differential pressure p_y is being built up in the line 53b, whereas line 53a has zero pressure.

In harmony with the automatic regulation of the angles α_k and α_e , fully described above with reference to Figs. 3 to 5, it has been assumed in the foregoing description of Fig. 7 that the switching-valve devices SCS, hydraulically connected with the rotary-slide control valve MCV of the machine, will operate under the full differential pressure p_2-p_1 and without any coaction of the pressure ratio regulators PRL, PRR if the machine is operating under the condition $+V_H, V_H/V_H\max.=1$, or $-V_H, V_H/V_H\max.$. In other words, the two ratio regulators are supposed to permit through-passage of the full pressure difference p_2-p_1 when $V_H=0$, i.e. when the ratio regulators have the neutral setting shown in Fig. 7.

In order to satisfy this requirement, the differential pressure regulator DPR as shown in Fig. 7 must meet the condition that the pressure p_x is zero or negligible, and that the area F_b is equal to the area F_a . With these pressure and area ratings, the differential pressure regulator DPR actually regulates the pressure p_y to be equal to the pressure difference p_2-p_1 , and the above-presented equation (Eq.) converts into the specific case: $p_y=p_2-p_1$.

It is often not desirable to operate the pressure regulating devices and the switching valve devices with the full operating pressure of the hydraulic machine. It is apparent from the equation (Eq.) that by suitably dimensioning the diameter ratio and hence the area ratio of the side pistons 50 and the middle piston 49, it is readily possible, when making $p_x=0$, to operate the same regulator as a differential ratio regulator whose lines 53a and 53b carry the respective pressures $p_y=F_a/F_b$ (p_2-p_1) and $p_y=0$, or vice versa. However, it is also readily possible to adapt the spring components of the slot-control switching devices SCS in accordance with a pressure, taken from the differential ratio regulator, which is proportional to the pressure difference p_2-p_1 but smaller than this difference. Any such modification of the differential pressure regulator does not necessitate a change in the design of the two pressure-ratio regulators PRL and PRR that are controlled by the stroke-length adjusting device of the hydraulic machine.

As described, the pressure p_y is supplied to the two ratio pressure regulators PRL, PRR from line 53a or line 53b through lines 37a and 37b, depending upon the operating condition of the hydraulic machine. It follows that it is necessary to prevent the two lines 53a, 53b from being in short-circuit connection with each other which would disturb the functioning of the differential pressure regulator. For this purpose, the two lines 53a and 53b according to Fig. 7 are connected with a hydraulically actuated change-over switch RS operating essentially like a three-way slide valve or a two-way valve. The change-over switch RS comprises a cylinder sleeve 54 closed at both ends, and a switching piston 55

oil-sealed and slidable in the cylinder sleeve. The pressure of respective lines 53a, 53b is passed upon the two axial ends of the switching piston 55 so that the obtaining pressure p_y always shifts that piston against a limiting stop in opposition to the force acting upon the other end of the switching piston and corresponding to the effective pressure (practically equal to zero) in the outlet line 52. During such displacement, the switching piston 55 uncovers a lateral port 56a or 56b of the cylinder sleeve 54, so that the pressure p_y , acting through the ports and through respective lines 37a, 37b and interconnecting line 57, is imposed upon both pressure ratio regulators PRL, PRR.

During each switching operation of the change-over switch RS, the switching piston 55 first covers one of the port openings 56a, 56b before it opens the other for the passage of the pressure p_y , and this prevents in all cases the occurrence of a hydraulic short circuit between the lines 53a and 53b thus securing the proper operation of the differential pressure regulator DPR.

If desired, the lines 39 coming from the pressure regulators PRL, PRR and carrying the pressures p_1 and p_2 could simply be connected to the respective sides of the cylinder sleeves of the slot-control switching devices SCS. A hydraulic multi-piston machine thus equipped would satisfactorily operate under all those operating conditions during which the (plus or minus) sign of V_H does not change. In practice, however, such change takes place with each hydraulic machine of this type when its piston-stroke varying control is displaced through the zero-stroke position into the range of the opposite direction of delivery; and this occurs even if, due to extraneous effects, the pressure difference p_2-p_1 at the control slots 1a, 1b of the valve control face changes its direction. Therefore, in order to have the noise reducing device according to Fig. 7 operate satisfactorily under all feasible operating conditions, the lines 39 carrying the pressures p_{z1} and p_{z2} are connected to two hydraulic reversing switches CS whose performance is essentially equivalent to two five-way valves or to four three-way valves, or to a single eight-way valve, and which accordingly may also be formed of the just-mentioned types of devices. In the embodiment of Fig. 7, the two hydraulic reversing switches CS comprise each a cylinder bore 58 of the regulator housing 36 and a control piston 59a or 59b oil-sealed and displaceable in the bore. In the illustrated example, the two control pistons are axially loaded by respective springs so that the piston bottoms are forced against the top of the cam member 42. Consequently, whenever the control lever 41 and cam member 42 are turned away from the neutral mid-position, the two switch pistons 59a, 59b are likewise displaced from their neutral mid-position upwardly or downwardly as the case may be. In this manner, the two hydraulic switches CS are so coupled with the stroke-length controls of the hydraulic machine that the switches operate in dependence upon the sign of V_H .

The control pistons 59a, 59b are each provided with two constricted portions 60 of the kind customary with five-way control valves. Each two lines 61a, 62a or 61b, 62b communicate with the respective control bores 58 and are in continuous connection with one of the constrictions 60 of the correlated control piston 59. These lines 61a, 62a and 61b, 62b serve for applying the respective pressures p_a and p_i to the switching devices.

The lines 39 coming from the pressure regulators PRL, PRR open each into one of the respective control bores 58 at such a location that the lines 39 are closed by the piston portion between the two constrictions 60 when the control pistons 58 are in mid-position as illustrated. When each control piston 58 is being displaced in one or the other direction, the line 39 communicating with the cylinder bore for that particular piston will communicate with one or the other constriction 60. An outlet line 63 is connected with a space of zero or negli-

gible pressure (such as atmospheric pressure), which space in the illustrated example is formed by the interior of the regulator housing 36. The outlet line 63 communicates with each of the two control bores 58 at two places so located that the outlet line 63 is just kept open by the control piston 59a or 59b when this piston is in mid-position but is closed when the piston performs a given amount of displacement, such closing being effected in dependence upon the direction of displacement by one or the other end portions of the correlated control piston 59a or 59b.

The two cam-controlled change-over switches CS operate as follows: In the illustrated neutral mid-position of control lever 41 and cam member 42, the lines 39 are completely closed. Each displacement of control lever 41 from the neutral position causes lifting of one and lowering of the other control pistons 59a, 59b. This causes the constrictions 60 of the pistons to connect the zero-pressure line 63 with one of the lines 61a, 62a and one of lines 61b, 62b, whereas the other one of these two pairs of lines is simultaneously connected with the line 39. Consequently, the left-hand pressure regulator PRL, when control lever 41 is turned into the positive range, supplies the line 61a with a pressure equal to p_a , and the right-hand pressure regulator PRR supplies to the line 62b a pressure equal to p_b , while the lines 62a, 61b are connected with the zero-pressure outlet line 63. On the other hand, when the control lever 41 is turned into the negative range, the left-hand pressure regulator PRL supplies the line 62a with a pressure equal to p_b , and the right-hand pressure regulator PRR supplies line 61b with a pressure equal to p_a , while the lines 61a and 62b are connected with the outlet line 63. When operating the hydraulic machine as a pump in CL rotation, the positive V_H -range in the example of Fig. 7 corresponds to a V_{za} value in the range of the upper half of the valve control face; and the negative range of V_H corresponds to V_{za} in the range of the lower half of the valve control face; and in each case the value V_{zi} is located on the opposite side.

The two hydraulic change-over switches CS actuated from the piston-stroke control of the hydraulic engine may also be combined into a single switching device whose control piston is then given a correspondingly greater length and is provided with all constrictions and ports for the switching of the hydraulic lines connected thereto.

Series connected, hydraulically, with the last-mentioned switches are two reversing-switch devices hydraulically actuated by the pressure p_y and having an over-all performance equivalent to that of two five-way valves or four three-way valves, or an eight-way valve. These two reversing-switch devices are combined with the above-described change-over switch RS so as to form a single multiple switch unit. This combination of switching means is obtained by giving the above-described switching piston 55 four constrictions 64a, 64b, 64c, 64d and providing the appertaining control sleeve 54 with the proper control ports. Accordingly, the constrictions 64a, 64b operate to switch lines 61a, 62a relative to their connection with the lines 66a, 66b leading to the cylinder sleeve 20e in device SCS; and the constrictions 64c, 64d control the connection of the lines 61b, 62b with the lines 66c, 66d leading to the cylinder sleeve 20f. Thus, each distribution of the pressures p_1 , p_2 onto the two control slots 1a, 1b is correlated to a given switch position of device RS and hence to a given connection of the hydraulic lines, which distribution always adjusts itself automatically because the hydraulic control of the multiple switching valve RS is dependent upon the two possible directions of the pressure difference $p_2 - p_1$ between the two control slots 1a and 1b.

The cooperation of all above-described components of the system according to Fig. 7 will be described presently in abbreviated form with reference to all possible operat-

ing conditions as listed in the table presented in the introduction of this specification.

Operation type 1a: Control slot 1a under pressure p_1 . Control slot 1b under pressure p_2 . Volume V_{za} occurs in the upper portion and volume V_{zi} in the lower portion of the valve control face. Control lever 41 is in the $+V_H$ -range. The differential pressure p_y obtains in line 53b, pushes the control piston 55 toward the left, passes from control sleeve 54 through port 56b, acts upon the two control pistons 32, and is converted by regulator PRL into the pressure p_a under control by the shallower cam portion of cam member 42. Pressure p_a acts through line 39, switch CS, line 61a, switch RS and line 66b upon the left end of piston slider 19e in SCS, while the right end of slider 19e is not pressure-loaded because it is connected with the interior of regulator housing 36 or a reservoir for the hydraulic working medium, through line 66a, switch RS, line 62a and the upper constriction 60 of the left-hand change-over switch CS. Piston slider 19e in the sleeve 20e moves toward the right until balance is established with the force of spring 13b. Thus, the piston slider 19e, depending upon the particular magnitude of p_a , disconnects a definite number of the auxiliary slots 2b, 3b, 4b, in the sequence here given, from the correlated main slot 1b. As a result, a positive compression angle α_k adjusts itself which results in the pressure balance required for reducing noise at the moment when a communication is established between the individual cylinder chambers of the machine with the control slot 1b. (For brevity, the moment just defined will be referred to as the "critical moment.")

The pressure regulator PRR modifies the pressure p_y under the effect of the steeper cam portion of cam member 42 into the pressure p_1 . Pressure p_1 acts through line 39, switch CS, line 62b, switch RS and line 66d upon the right end of piston slider 19f, while the left end of slider 19f is not under pressure because it is connected with the interior of the regulator housing 36 through line 66c, switch RS, line 61b and the lower constriction 60 of the right-hand change-over switch CS. As a result, the piston slider 19f moves toward the left until equilibrium is established with the force of spring 13d. Slider 19f thus disconnects from the control slot 1a a given number of auxiliary slots 2d, 3d, 4d in the sequence here given, the number depending upon the magnitude of p_1 . In this manner, a positive expansion angle α_e adjusts itself which results in the pressure balance required for noise reduction at the critical moment of commencing communication between the slot 1a and the cylinder chamber of the machine.

Operation type 1b.—Compared with type 1a, the hydraulic machine merely changes its direction of rotation from CL to ACL and runs, not as a pump, but as a motor. The above-considered compression angle $+ \alpha_k$ in the right upper portion of the valve control face now becomes the expansion angle $+ \alpha_e$; the above-considered expansion angle $+ \alpha_e$ in the left lower portion of the valve control face becomes the compression angle $+ \alpha_k$; and all operations of the system remain otherwise as described above.

With all possible conditions of operation according to the above-presented table, the angles α_k and α_e on the V_{zi} -side of the valve control face are equal to each other; and there is also equality of the angles α_k and α_e on the V_{za} -side of the control face.

Operation type 11a.—Pressure p_1 in control slot 1b, pressure p_2 in slot 1a. Volume V_{za} occurs in the lower portion, and volume V_{zi} in the upper portion of the valve control face. Lever 41 is in the $-V_H$ -range. The difference pressure p_y occurs in line 53a, moves the switching piston 55 of reversing switch RS to the right, acts in sleeve 54 through port 56a and onto the two respective pistons 32 of pressure regulators PRL and PRR. Regulator PRL converts pressure p_y into the pressure p_1 under control by the steeper cam curve of member 42. Pressure p_1 acts through line 39, switch CS, line

62a, switch RS and line 66b onto the left end of piston slider 19e in slot control switch SCS, while the right end of slider 19e is simultaneously connected with zero pressure, namely with the interior of regulator housing 36, through the line 66a, switch RS, line 61a and the lower constriction 60 of switch CS (left). As a result, piston slider 19e moves in sleeve 20e of SCS toward the right up to the point where balance occurs with the force of spring 13b. Thus the slider 19e separates a certain number of the auxiliary slots 2b, 3b, 4b, in this sequence, from the main slot 1b, this number depending upon the magnitude of p_1 . In this manner, a positive compression angle α_k is adjusted which results in the equalization of pressure required for noise reduction at the critical moment of commencing communication between an individual cylinder of the machine with the control slot 1b.

The pressure regulator PRR modifies the pressure p_y into the pressure p_a under control by a shallower cam curve of member 42. Pressure p_a acts through line 39, switch CS, line 61b, switch RS and line 66d onto the right end of piston slider 19f in slot control switch SCS, while simultaneously the left end of slider 19f is connected with zero pressure through line 66c, RS, line 62b and the upper constriction 60 of switch CS (right). Consequently, the piston slider 19f moves toward the left, up to the point of balance with the force of spring 13d and thus hydraulically disconnects a number of auxiliary slots 2d, 3d, 4d, in this sequence, from the main slot 1a, this number depending upon the magnitude of p_a . Thereby a positive compression angle α_k is adjusted which results in the pressure equalization required for noise reduction at the critical moment relative to slot 1a.

Operation type IIb.—In this case, the hydraulic machine, compared with operation type IIa, merely changes its direction of rotation from CL to ACL and runs as a motor. The compression angle $+\alpha_k$ in the left lower quadrant of the valve control face now becomes the expansion angle $+\alpha_e$, the previously considered expansion angle $+\alpha_e$ in the right upper quadrant becomes the compression angle $+\alpha_k$; and all switching operations of the system remain otherwise unchanged.

Operation type IIIa.—Pressure p_1 in control slot 1b, p_2 in slot 1a. Volume V_{2a} in upper portion, volume V_{2l} in lower portion of valve control face. Lever 41 in range $+V_H$. The difference pressure p_y occurs in line 53a, shifts the switching piston 55 in RS toward the right, passes through sleeve 54 and port 56a, and acts upon the two pistons 32 of PRL and PRR. Regulator PRL converts p_y into pressure p_a under control by the shallower cam curve of member 42. Pressure p_a acts through line 39, CS, line 61a, RS and line 66a upon the right end of piston slider 19e in SCS, while the left end of piston 19e is connected to zero pressure through line 66b, RS, line 62a and the upper constriction 60 of switch CS (left). As a result, the slider 19e moves toward the left in sleeve 20e of SCS until balance is obtained with the force of spring 13a and, depending upon the magnitude of p_a , disconnects a number of the auxiliary slots 2a, 3a, 4a, in this sequence, from the main slot 1a. As a result, a negative compression angle α_k adjusts itself for equalization of pressure at the critical moment of commencing communication between an individual cylinder chamber and the control slot 1a.

The pressure regulator PRR modifies the pressure p_y into the pressure p_1 under control by the steeper curve of cam member 42. Pressure p_1 acts through line 39, switch CS, line 62b, switch RS and line 66c upon the left end of piston slider 19f in switch SCS, while the right end of the same piston slider is connected with zero pressure through line 66d, RS, line 61b and the lower constriction 60 of CS (right). The piston slider 19f in switch SCS moves toward the right until balance is established with the force of spring 13c and thus separates, in dependence upon the magnitude of p_1 , a corresponding number of

the auxiliary slots 2c, 3c, 4c, in this sequence, from the main slot 1b, whereby the proper negative expansion angle α_e is adjusted as required for pressure equilibrium at the critical moment of commutation.

- 5   *Operation type IIIb.*—Compared with type IIIa, the hydraulic machine only changes its direction of rotation from ACL to CL and runs as a motor. The previous compression angle $-\alpha_k$ in the upper left quadrant of the valve control face now becomes the expansion angle $-\alpha_e$, the previous expansion angle α_e in the lower right quadrant becomes the compression angle $-\alpha_k$; otherwise all switching operations of the system remain unchanged.
- 10   *Operation type IVa.*— p_1 obtains in control slot 1a, p_2 in slot 1b. Volume V_{2a} is located below, V_{2l} above at the valve control face. Lever 41 is in range $-V_H$. The difference pressure p_y occurs in line 53b, pushes the piston 55 of switch RS toward the left, acts through sleeve 54 and port 56b upon the two pistons 32 of PRL and PRR. PRL converts p_y into p_1 under control by the steeper cam curve of member 42. Pressure p_1 acts through line 39, CS, line 62a, RS and line 66a upon the right end of piston slider 19e in SCS, while the left end of the same piston is connected to zero pressure through line 66b, RS, line 61a and the lower constriction 60 of CS (left). The piston slider 19e in sleeve 20e moves toward the left until balance is reached with the force of spring 13a, and thus disconnects, in dependence upon the magnitude of p_1 , a corresponding number of the partial slots 2a, 3a, 4a, in this sequence, from control slot 1a.
- 25   As a result, a negative expansion angle α_e is adjusted as required for pressure equalization at the critical moment.

Regulator PRR modifies pressure p_y into p_a under control by the shallower cam curve of member 42. Pressure p_a acts through line 39, RS, line 61b, and line 66c upon the left end of piston slider 19f in SCS, while the right end of slider 19f is connected to zero (atmospheric) pressure through line 66d, RS, 62b, and the upper constriction 60 of switch CS (right) or the control piston 59a of switch CS. Piston slider 19f, under pressure p_a , moves to the right up to equilibrium with spring 13c and thus disconnects, in dependence upon the magnitude of pressure p_a , a given number of the auxiliary slots 2c, 3c, 4c, in this sequence, from the main slot 1b, whereby the proper negative compression angle α_k is adjusted.

35   *Operation type IVb.*—Compared with operation type IVa, the hydraulic machine changes its direction of rotation from ACL to CL and runs not as a pump but as a motor. The previous compression angle $-\alpha_k$ in the lower right quadrangle of the valve control face becomes the expansion angle $-\alpha_e$, the previous expansion angle in the left upper quadrant becomes the compression angle $-\alpha_k$; otherwise all switching operations of the system remain unchanged.

FIG. 8

The noise reducing apparatus for multi-piston machines illustrated in Fig. 8 comprises a rotary slide valve MCV and a slot control switch SCS corresponding to those illustrated in Figs. 4 and 7 and described in the foregoing. The apparatus of Fig. 8 is likewise suitable for all types of operation listed in the above-presented table. An essential difference, compared with the embodiment of Fig. 7, resides in a particular design of the mechanically controlled pressure regulators PRL and PRR which, in the system of Fig. 8, simultaneously function as the series-connected and likewise mechanically actuated change-over switch (CS in Fig. 7) and thus afford a simplification of the entire system.

The two pressure regulators PRL, PRR are of identical design. Each comprises two cylinder bores 70a and 70b of the regulator housing 71, and two respective control pistons 72a and 72b, oil-sealed and displaceable in the cylinder bores, which have their illustrated lower end abut against the two respective arms of a teeter 73.

The teeter 73 is pivotally mounted on a swing arm 74

linked at 74' to the regulator housing structure 71. This mounting of teeter 73 permits varying the effective ratio of the two lever arms of the teeter relative to pistons 72a and 72b. Rotatably mounted in the regulator housing 71 is a V-shaped lever whose two arms 75a and 75b are rigidly connected at their pivot shaft 76 with a control lever 41 that extends out of the regulator housing. The swing arms 74 of regulators PRL and PRR are connected through respective linking rods 77 with the respective arms 75a and 75b. The control lever 41 is connected by a suitable transmission with the piston-stroke adjusting device of the hydraulic machine as explained above with reference to the embodiment of Fig. 7.

The V-structure of the lever arms 75a, 75b causes an unequal angular displacement of the two swing arms 74, namely in such a manner that, for instance, when control lever 41 is turned toward the left into the $+V_H$ -range up to the indicated dot-and-dash limit position, the leverage ratio of the pistons in pressure regulator PRR departs from the illustrated ratio 1:1 only slightly, whereas the corresponding leverage ratio in the pressure regulator PRL changes to a much greater extent. The entire linking mechanism is such that when the control lever 41 is moved out of the illustrated mid-position, the leverage ratio in one pressure regulator is regulated in accordance with the ratio p_y/p_1 and in the other regulator in accordance with the ratio p_y/p_a , the regulation in both regulators being dependent upon the then obtaining ratio V_H/V_H max. The control pistons 72a, 72b are all of identical design and are each equipped with two constrictions 78a and 79a or 78b and 79b. The control pistons are further traversed by bores 80 which continuously connect the upper constriction 78a or 78b with the enclosed space at the upper end of the cylinder bores 70a or 70b.

Each of the pistons of regulators PRL and PRR has three lateral ports, such as those connected in regulator PRL with respective lines 37, 40 and 62b. The three lines laterally extending from each piston correspond, as to function, to those denoted by the same respective reference characters in the embodiment of Fig. 7.

The operation of the pressure regulators PRL and PRR in the system of Fig. 8 is as follows:

In the illustrated neutral mid-position, corresponding to zero stroke of the hydraulic machine, the effective teeter arms for both pistons 72a and 72b in each regulator PRL, PRR are of equal length, so that the pressure p_y supplied to the constrictions 78a, 78b through line 37 is transmitted through the respective bores 80 to above the upper end face of the respective pistons 72a, 72b. Consequently, the two pistons in each regulator produce equal and mutually opposed torques in teeter 73. The two regulator pistons are in labile equilibrium which, if desired, can be modified into stable condition by locating the teeter pivot slightly away from the accurate center of the teeter axis extending between the respective lower ends of the two pistons.

As soon as the control lever 41 is turned from the neutral position toward the left into the $+V_H$ -range, the teeter pivot point in both pressure regulators shifts toward the right. Thus the leverage ratio of each teeter changes in favor of control piston 72a which produces a preponderant torque and moves downward while displacing the other piston 72b upward. In regulator PRL, the constriction 78a now connects the line 37, under pressure p_y , with the line 62b, and the constriction 79b connects the zero-pressure line 40 with the line 61b. In regulator PRR, the constriction 78a now connects line 37 with line 61a, and the constriction 79b connects line 40 with line 62a. The lines 61a, 62a and 61b, 62b are connected through respective four constriction portions of a hydraulically operated reversing switch RS and through respective further lines 66a, 66b and 66c, 66d with the slot-control switch device SCS of the rotary slide

valve MCV, in the same manner as in the embodiment of Fig. 7 and explained above.

Consequently, the lines 61a and 62b are under increasing pressure. However, as soon as the regulating pressure p_1 or p_a exceeds the ratio value of p_y determined by the instantaneous leverage ratio of the teeter, the pistons 72a in regulators PRL and PRR produce a further excess torque and move still further downward until they close the supply from the line 37 and terminate the 10 regulating operation.

Both pressure regulators PRL, PRR simultaneously react to any variation of p_y or V_H/V_H max. For example, if p_y increases, the pistons 72b connected with line 15 37 produce excessive torque, and the constrictions 78a of the pistons 72a permit the flow of pressure medium from line 37 into lines 61a, 62b until in the latter lines the new pressure values p_1 and p_a corresponding to the changed value of p_y have been built up. On the other hand, if the pressure p_y decreases, the two pistons 72a 20 immediately produce an excessive torque and shift downward from their normal position of rest. As a result, the lines 61a, 62b already disconnected from line 37 in the previous position of rest, are now connected through the constrictions 78a with the zero-pressure line 40, so 25 that the pressure p_1 or p_a in lines 61a and 62b will drop until torque balance occurs and a reverse movement of the pistons 72a again closes the just-mentioned outlet connection.

If the instantaneous equilibrium of the two pistons 72a, 30 72b in each regulator PRL, PRR is disturbed by a variation in the ratio V_H/V_H max. as may be caused by the lever 41 being turned farther into the $+V_H$ -range, then such disturbance corresponds to a change in the leverage ratio at the teeter 73 in favor of the piston 72a. The 35 resulting excess torque at piston 72a permits the pressure medium to escape from lines 61a, 62b into the outlet line 40 until the pressures in lines 61a, 62b again correspond to the datum value of p_a or p_1 . If, conversely, the control lever 41 is displaced in the direction toward zero 40 position, then the leverage ratio of the teeters changes in favor of the pistons 72b and these pistons, loaded by p_y , move downward and, acting through the teeter, shift the respective pistons 72a upward. The resulting connection of lines 62b and 61a with line 37 causes a pressure increase of p_1 and p_a respectively. This pressure increase is terminated by a downward movement of the 45 control pistons as soon as the torque balance and hence the correct datum value of the pressure is attained.

The foregoing considerations relate to a displacement 50 of control lever 41 into the $+V_H$ -range. In contrast, when lever 41 is shifted from zero position into the negative range of V_H , which corresponds to a reversal of the delivering direction of a pump or to reversal in direction of rotation of a motor, then a change-over switching 55 must take place to make the lines 61b, 62a carry the regulator pressures p_a and p_1 , and to now place the lines 61a, 62b under zero pressure. In the apparatus according to Fig. 8 such change-over switching takes place automatically. This is so because when lever 41 is being 60 moved into the negative range of V_H , the pistons 72b always act upon the longer leverage arm and hence now reverse the previously explained functioning with that of the pistons 72a. As a result, in the negative range of V_H of the hydraulic machine, the lines 61a, 62b are 65 continuously connected with the outlet line 40, and the pistons 72a are continuously loaded by the pressure p_y .

No further explanation need be given of all individual switching operations occurring during pressure regulation, as these operations accurately correspond mirror-symmetrically to those already set forth relative to the 70 positive adjusting range. Summarizing, however, it may be mentioned that always those pistons that, in the pressure regulator PRL and PRR, have the shorter leverage arm connect one of the respective lines 61a, 62a or of 75 respective lines 61b, 62b with the zero-pressure line 40

and are continuously loaded at the piston end by pressure p_y , while simultaneously the regulator pistons having the longer leverage arm connect the lines of groups 61a, 62a or 61b, 62b either with the line 37 carrying the pressure p_y or with the zero-pressure line 40, thus regulating the pressures p_1 and p_a to the magnitudes that correspond to the respective angles α_k and α_e in accordance with the above-presented equation (Eq.). The latter pistons, namely those acting upon the longer leverage arm, then separate the groups of lines 61a, 62a or 61b, 62b from both lines 37 and 40 when the balance condition is reached, and these pistons are continuously loaded at their respective ends by the one pressure p_1 or p_a regulated by the particular piston.

It may further be mentioned that, as explained with reference to the embodiment of Fig. 7, one of the two pressure regulators PRL or PRR regulates the pressure p_1 and the other the pressure p_a in the positive regulating range of V_H ; whereas in the negative range of V_H the former pressure regulator regulates the pressure p_a and the latter regulator the pressure p_1 . Simultaneously with a change of operation from one V_H -range into the other, the correct change in correlation between V_{z1} , V_{za} and p_1 , p_a is automatically secured.

The pressure regulators PRL, PRR in the respective embodiments according to Figs. 7 and 8 can be readily exchanged for each other. This also applies to the series-connected, hydraulically actuated multiple switching valve RS. In Fig. 8, the switching device RS differs from the one shown in Fig. 5 only by the fact that the alternating connection of the lines 53a, 53b with the line 37 is effected not at the ends of the switching piston 55 but by means of a particular constriction 81 in the middle of the piston. The performance of the device corresponds to a three-way control valve and a two-way control valve.

In further distinction from the embodiment of Fig. 7, it is shown in Fig. 8 that the multiple switching device RS, instead of being controlled by the pressure p_y as is the case in the apparatus of Fig. 7, may be controlled independently of p_y in response to the pressure $p=p_2-p_1$. For this purpose, the two closed ends of the cylinder sleeve 54 in device RS (Fig. 8) are directly connected to the lines 46a and 46b coming from the rotary-valve control slots 1a and 1b respectively. The operation of the multi-switching device RS remains unchanged. The differential pressure regulator DPR in Fig. 8 also corresponds to that in the above-described apparatus of Fig. 7; and the over-all performance of the noise reducing system as a whole is identical with that described in detail above with reference to Fig. 7. The performance for the various types of operation can be readily traced with reference to the description given relative to Fig. 7, as all reference characters used in both illustrations and relating to respectively similar components are identical.

FIG. 9

Fig. 9 illustrates an embodiment of a device, applicable as a component of the noise reducing apparatus described above as well as hereinbelow, which constitutes one of the possibilities of combining the differential pressure regulator (DPR) with the multiple switching device (RS). In the combined device DPR—RS of Fig. 9, the stepped pistons (49, 50, DPR, Figs. 7 and 8) and the control piston of the multiple switching device (55 of RS in Figs. 7, 8) as well as the cylinders 48a, 47, 48b and the control sleeve 54 are combined to a single unit. As shown in Fig. 9, the device DPR—RS comprises a cylinder sleeve 82 in which a piston 83 with five constrictions is displaceable. The cylinder sleeve 82 is joined with lateral cylinders 48a, 48b in which respective lateral pistons 50 are likewise displaceable, each lateral piston being integral or joined with the main piston 83. The lateral cylinders 48a, 48b are connected to the respective lines 46a, 46b coming from control slots 1a and 1b. Two lines 52a and 52b, both communicating

with the outlet line 52, are connected to the cylinder sleeve 82 at two port locations closely adjacent to the respective end faces of the control piston 83. Two lines 53a, 53b communicating laterally with the respective lateral cylinders 48a, 48b are connected with respective control ports 56a, 56b of the cylinder sleeve 82 at points located on opposite sides of the constriction 81 of the control piston 83.

The constriction 81 is in continuous connection with the line 37 which supplies the pressure p_y to the pressure regulators (PLR, PRR in Figs. 7, 8). The other four constrictions of piston 83 perform exactly the same functions as the constrictions of the multiple switching devices RS already described with reference to the embodiments of Figs. 7 and 8.

A combined device DPR—RS according to Fig. 9 operates in its differential pressure regulating portion exactly in accordance with the above-presented equation (Eq.) as is the case with the corresponding component DPR of the embodiments previously described. The other portions of the control piston operate exactly in the same manner as the component RS in the embodiments of Figs. 7 and 8. This can be readily checked since the same reference numerals are used in Fig. 9 as in the corresponding portions of Figs. 7 and 8. The cross section of the control piston 83 (Fig. 9) corresponds to the middle piston portion 49 (Figs. 7, 8); and the cross section of the lateral pistons 50 in Fig. 9 corresponds to the cross section of the lateral pistons 50 in Fig. 7 or Fig. 8. Thus, the overall performance of the combined regulating and switching device according to Fig. 9 corresponds to that of the two devices DPR and RS previously described in detail.

FIG. 10

Fig. 10 shows schematically a two-circuit differential-ratio pressure regulator DPR which permits actuating the slot control device SCS from an extraneous source of pressure, and using the hydraulic-machine pressures p_1 and p_2 only as controlling magnitudes. The advantage of such a differential regulator resides in the fact that its operation does not affect the circulation of the hydraulic medium delivered to or by the hydraulic machine being controlled, as compared with the fact that, when the actuating pressure is taken from the high-pressure circulation of the machine, the regulating devices, for instance during the operation of the pressure regulators, permit some, though slight, escape of high-pressure oil into the zero-pressure space. Hydraulic plants and assemblies, such as hydrostatic drives, are often provided with an auxiliary pump for replenishing leakage oil losses; and by suitably rating the area ratio F_a/F_b in equation (Eq.) it is readily possible to make the above-described slot-control devices SCS for controlling the angles α_k and α_e suitable for operation by the operating pressure of the leakage oil pump. In this connection it is important that, as long as the latter pressure is not smaller than the highest occurring pressure p_1 or p_2 , the magnitude of the leakage oil pressure has no effect upon the latter two regulating pressures.

The differential pressure regulator DPR according to Fig. 10 is provided with a middle cylinder 85 in which a middle piston 86 is displaceable. Joined together with the middle cylinder at both ends thereof are respective smaller cylinders 48a and 48b in which respective lateral pistons 50 are slidable. The pistons 50 are continuously loaded through lines 46a and 46b by the pressures obtaining in respective control slots 1a and 1b. The middle piston 86 has two grooves 87a, 87b. Groove 87a is connected through a slanting bore 88 with the right-hand end side, and groove 87b is connected through a slanting bore 88 with the left-hand end of the middle piston 86, these hydraulic connections being always open. The middle piston 86 has slight axial clearance within the middle cylinder 85. Connected to the respective

ends of the middle cylinder 85 are the above-mentioned lines 53a and 53b which carry the pressure p_1 (as explained with reference to Fig. 8). The two branches 52a, 52b of the outlet line 52 have respective port openings located closely ahead of the outermost end faces of the middle piston when this piston is in the illustrated mid-position. Line 89, carrying the auxiliary pressure p_x , communicates with the middle cylinder 85 at a port location in the middle of the latter cylinder.

The operation of the device is as follows: Pressures p_1 and p_2 act upon the respective lateral pistons 50. The resulting differential force displaces the entire piston assembly always to the side loaded by p_1 . This causes the middle piston 86 to immediately close one of the outlet lines 52a, 52b so that a closed ring-shaped space is formed from which the line 53a or 53b transmits the ring-space pressure, as the pressure magnitude p_y , to the further switching and regulating devices. However, it is first necessary to form the pressure p_y ; and this done during the further displacement of the middle piston in the following manner. The auxiliary liquid delivered from the leakage oil pump or the like extraneous pressure source, having the pressure p_x , passes through line 89 into the groove 87a or 87b so that the auxiliary hydraulic medium flows into the above-mentioned ring space separated from the outlet line. Consequently the pressure in the ring space increases. When this pressure exceeds the magnitude p_y according to the equation (Eq.), the force composed of $F_b \cdot p_y$ and $F_a \cdot p_y$, again displaces the piston assembly in the reverse direction in opposition to the force $F_a \cdot p_y$, until the middle piston again covers the line 89 carrying the pressure p_x . This play repeats itself with each increase in the pressure difference $p_2 - p_1$. When the difference pressure $p_2 - p_1$ decreases, the middle piston continues its return motion until its end face uncovers the particular branch of line 52 then connected with the one ring space carrying the pressure p_y . As a result, the pressure p_y in the ring space is reduced to the portion of difference pressure $p_y - p_1$ that corresponds to the ratio F_a/F_b . The described differential pressure ratio regulator can readily be used in systems according to Fig. 7 or Fig. 8.

FIG. 11

Fig. 11 shows schematically a differential pressure-ratio regulator for two hydraulic circuits, which as regards performance is fundamentally similar to that of Fig. 9 in combining the multiple switching device (RS) with the differential pressure-ratio regulator (DPR). The regulator DPR-RS according to Fig. 11 further offers the possibility to operate the regulating devices without high-pressure oil losses and with the aid of an auxiliary pressure medium supplied from an extraneous source of much lower pressure such as a leakage oil pump or the like. In this respect the regulating device according to Fig. 11 may also be looked upon as combining a device according to Fig. 9 with a device as shown in Fig. 10.

As apparent from Fig. 11, the hydraulic cylinder sleeve 82 and the two annexed lateral cylinders 48a, 48b, as well as the two lateral pistons 50 and the main control piston 83 between them, correspond, as to operation, to the components designated in Fig. 9 by the same respective reference characters. The hydraulic lines in Fig. 11 are also designated by the same respective reference characters as the corresponding components in Fig. 9. It will be recognized that the device of Fig. 11, as was the case with the one shown in Fig. 9, is readily applicable in a system according to Fig. 7 or Fig. 8 and, if so used, will serve the purposes of the differential pressure regulator DPR and of the multiple switching device SR shown in the latter two illustrations.

The control piston 83 in Fig. 11 is provided with five constrictions and, in cooperation with the cylinder sleeve 82, has a performance equivalent to three five-way con-

trol valves or six three-way valves or a single twelve-way valve. A difference, compared with the embodiment of Fig. 9, is the fact that the liquid pressure medium for actuating the regulating device is not supplied to lines 46a, 46b through lateral ports of the lateral cylinders 48a, 48b, but is taken from a line 89, under the pressure p_x , which has respective branch lines 89a, 89b opening into the cylinder sleeve 82 on opposite sides respectively of the middle constriction 81 of the regulator piston when the latter is in the illustrated mid-position. The axial spacing between the port openings of lines 56a and 56b is somewhat smaller, and the corresponding spacing between the port openings of lines 89a and 89b somewhat larger than the axial width of the constriction 81. In the illustrated mid-position of piston 83, the line 37 communicates through lines 56a, 52b, 56b, 52a with the outlet line 52 and thus becomes relieved of the pressure p_y . The middle line 37, continuously connected with the constriction 81, supplies the pressure p_y to the two pressure regulators (PRL, PRR in Figs. 7, 8).

Operation: Assume p_2 obtains in line 46a, p_1 in line 46b. Then the difference pressure $p_2 - p_1$ pushes the lateral pistons 50 and the main piston 83 from the illustrated mid-position toward the right. The left control edge of constriction 81 first closes the port opening of line 56b, and the right end of piston 83 simultaneously closes the port opening of outlet line 52b. Thereafter the right control edge of the same constriction 81 uncovers the port opening of line 89a. Now the pressure medium, under the pressure p_x , can flow from line 89 into constriction 81 and thence through line 56a into the ring space at the right-hand side of the control piston and also into the line 37 where a pressure increase is caused thereby.

However, as soon as the regulator pressure p_y in line 37 exceeds the datum value according to the above equation (Eq.), then the forces loading the control piston toward the left will preponderate and return the piston toward the left until the right-hand control edge of constriction 81 again covers the port opening of line 89a. For each increase of the pressure drop $p_2 - p_1$ the same play repeats itself. However, if the pressure drop $p_2 - p_1$ decreases during operation of the hydraulic machine, then the pressure p_y must again be reduced to that portion of the difference pressure $p = p_2 - p_1$ which corresponds to the rated ratio of the piston cross sections. The preponderance, resulting from decreasing difference pressure p of the hydraulic forces loading the control piston toward the left, has the effect of displacing the control piston 83 toward the left until the right-hand end of the piston uncovers the port opening of the branch 52b of outlet line 52, and if the drop of the difference pressure p is rapid, the left-hand control edge of the constriction 81 also uncovers the port opening of the line 56b. The pressure medium can now escape from line 37 into outlet line 52 until the pressure ratio, when the difference pressure p drops below the datum value of p_y , has again changed in favor of a piston displacement toward the right. The control piston 83 then again moves toward the right into that position in which the port opening of line 89a just remains covered; and from here on each of the above-described regulating plays can repeat itself in accordance with any particular change in the value of the difference pressure p .

If the pressure difference $p = p_2 - p_1$ changes its direction so that p_2 occurs in line 46b, and p_1 in line 46a, then the above-described regulating operations take place in the same manner at the symmetrically located ports. Hence it will be unnecessary to describe these analogous operations in further detail. The four outer constrictions of piston 83 serve for reversely switching the lines 66a, 66b and 66c, 66d independently of the above-described pressure regulation.

During all regulating operations or in all operating positions of the devices according to the embodiment of

31

Fig. 7 or Fig. 8, the slot-control switch devices SCS have always one end of each piston slider relieved of pressure down to the pressure of the outlet line 52 and hence down to about ambient atmospheric pressure, whereas the other end face is loaded by the pressure p_1 when regulating the angles α_k or α_e on the V_{21} -side of the valve control face, and by the pressure p_2 when regulating the angles α_k and α_e on the V_{22} -side of the valve control face.

As explained above, the term "line" is meant to define any means for conducting a flowing pressure medium. It should further be understood that the hydraulic circuitry explained with reference to the examples of Figs. 1 through 11 is not limited to the particular constructions and arrangements illustrated. For example, any kind of the slide-valve control devices illustrated by way of example can be substituted by other known types of control valves of equivalent performance.

FIG. 12

Fig. 12 shows schematically a complete system of noise reduction which is likewise suitable for use with multi-cylinder machines of variable volumetric delivery and variable delivering direction, and which permits being operated in accordance with all types of operation listed in the foregoing table.

The control and switching devices SCS, DPR, CS, PRL, PRR of the system, as regards their interconnections, correspond to those shown in Figs. 4, 7 and 8, although these devices may also be substituted by component devices as shown in Figs. 3 and 5.

The regulating housing 36 in the system shown in Fig. 12 is provided with four individual pressure regulators denoted by PRL I and II, PRR III and IV. As to design and operation, these regulators correspond to those shown in Fig. 7 and described above. The four regulators I, II, III, IV, are controlled jointly from the piston-stroke setting device of the hydraulic machine by means of a control lever 41 which is linked to the just-mentioned device and is pivotally mounted in the regulator housing 36. The control lever 41 is rigidly joined with a rotatable cam member 91 which acts during operation of the hydraulic machine in the $+V_H$ -range to vary the leverage ratio of the ratio pressure regulators I and II in accordance with a function dependent upon the ratio $V_H/V_{H\max}$ so as to result in the regulated angles α_{k1} and α_{e1} . Simultaneously, the cam member 91 controls the ratio of the ratio pressure regulators III and IV in accordance with the same regulating function to produce the angles α_{k2} and α_{e2} . Analogously, during operation of the machine in the $-V_H$ -range, the cam member 91 varies the transmission ratio of the pressure regulators I and II in accordance with a function dependent upon $V_H/V_{H\max}$ to result in the angles α_{k1} and α_{e1} , while simultaneously varying the transmission ratio of regulators III and IV in dependence upon the same function to produce the angles α_{k2} and α_{e2} .

For this purpose, the two swing arms 35 of the ratio pressure regulators I and II are interconnected by a linking rod 99, and the swing arms 35 of regulators III and IV are also interconnected by a linking rod 99. Each linking rod 99 is loaded by a pressure spring 100 in the direction toward the cam member 91 so that a cam roller 45 journaled on the linkage assembly is biased against the cam contour. For each of the two pairs of pressure regulators I, II and III, IV the cam member 91 has a cam contour composed of a shallow and a steep curve portion.

In the illustrated mid-position of control lever 41 and cam member 91 the two rollers 45 are just located at the junction point of the two component cam curves on the respective two sides of the member 91. In this position of cam member 91 each of the two teeters 34 has a leverage ratio of 1:1, and this corresponds to a regulated pressure ratio likewise of 1:1. Each displacement

32

of cam member 91 from the illustrated neutral mid-position causes a displacement of the teeter pivot points to an extent determined by the cam contour of member 91 and in a direction toward the cam member 91. Such displacement causes all ratio pressure regulators to produce the desired reduction in pressure as determined by the curve shape of cam member 91. The pressure reduction ratio in pressure regulators I and II is equal to that in the regulators III and IV.

- 10 The cam member 91 simultaneously actuates two control pistons 93a, 93b of hydraulic switch CS. Each of the two pistons is provided with a constriction 94 and is guided in a cylinder bore 101 of the regulator housing 36 and axially loaded by a spring 102. Each of the 15 control pistons 93a, 93b forms essentially a three-way switch together with three control ports in each cylinder bore 101. The entire regulator group is subjected to the pressures p_1 and p_2 instantaneously obtaining in the control slots 1a and 1b of the rotary slide valve MCV. 20 For this purpose, the pressure of slot 1a passes through a line 46a and thence through a line 95a simultaneously to the lowermost control ports of both switch components of CS. Analogously, the pressure from slot 1b passes through line 46b and thence through line 95b 25 to the two upper control ports of both switch components CS. When the cam member 91 is displaced into the $+V_H$ -range, the constriction 94 of control piston 93 connects line 95a through line 96a with the ratio pressure regulators II and IV; and the constriction 94 of piston 93b simultaneously connects the line 95a 30 through line 96b with regulators I and III.

However, when cam member 91 is displaced into the $-V_H$ -range, the constriction 94 of control piston 93 connects line 95a through line 96a with the pressure regulators II and IV; and constriction 94 of piston 93b connects line 95b through line 96b with regulators I and III. The regulating pressure produced by regulator I is supplied through line 66a to the spring space 22a in slot control switch SCS. The regulating pressure produced by regulator II passes through line 66b to the spring space 22b. The regulating pressure delivered by regulator III passes through line 66c to spring space 22c; and the regulating pressure produced by regulator IV passes through line 66d to spring space 22d.

45 The operation of the system as a whole will be described presently with reference to the types of operation listed in the foregoing table.

Operations types Ia and Ib: Control lever 41 and cam member 91 in $+V_H$ -range. Control slot 1b is connected with spring space 22b of SCS through lines 46b, 95b, piston 93a and regulator II; and slot 1b is also connected with spring space 22b through regulator IV. Control slot 1a is connected through 46a, 95a, 96b and regulator I with spring space 22a, and is also connected 50 through regulator III with spring space 22c. p_1 acts in control slot 1a, p_2 in control slot 1b. Consequently, the always larger regulating pressures derived from p_2 shift the piston 19e in slot-control switch SCS toward the right so that it closes the auxiliary slots 2b, 3b and maintains 55 the auxiliary slots 2a, 3a fully connected with the main control slot 1a. Simultaneously, the always higher regulating pressures derived from p_2 , acting in opposition to the always lower regulating pressures derived from p_1 , force the piston slider 19e toward the right and the piston slider 19f toward the left. Slider 19e then controls the auxiliary slots 2b, 3b and piston slider 19f controls the auxiliary slots 2d and 3d. The auxiliary slots 2a, 3a and 2c, 3c remain entirely unaffected and hence remain connected with the respective main control slots 1a and 1b.

During CL-rotation of the slide-valve member gliding upon the valve control face, the just-mentioned regulating conditions correspond to the operation type Ia; and the slots 2b, 3b are regulated in accordance with the com-

pression angle α_{ka} and the slots 2d, 3d in accordance with the expansion angle α_{ea} .

During ACL-rotation, the above-described regulating conditions correspond to the operation type Ib; the auxiliary slots 2d, 3d are regulated in accordance with the compression angle α_{el} and the slots 2b, 3b in accordance with the expansion angle α_{ea} .

Operation types IIa and IIb.—When during operation the adjustment of the hydraulic machine is changed from the $+V_H$ -range into the $-V_H$ -range, then the machine converts to the operation type IIa. When operating the machine as a pump in CL-rotation (type IIa), the pressure p_1 obtains in control slot 1b, and p_2 in control slot 1a. Simultaneously, however, the switching position of change-over switch CS changes. This has the consequence that the regulating pressures derived by regulators II and IV from the pressure p_1 of control slot 1a, and derived by the regulators I and III from the pressure p_1 of control slot 1b, again displace the piston slider 19e toward the right and the piston slider 19f toward the left, however with the difference that now the piston slider 19e regulates a positive expansion angle α_{el} and the piston slider 19f the positive compression angle α_{ka} . If under these conditions the direction of rotation changes from CL to ACL, then the hydraulic machine, with an otherwise unchanged setting of the regulation, performs the operation type IIb and runs as a motor. The piston slider 19e, displaced toward the right as before, now regulates the positive expansion angle α_{ea} , and the piston slider 19f, displaced toward the left as before, regulates the positive compression angle α_{ka} .

Operation type IIIa.—ACL-direction of rotation. Operation as a pump. p_1 in slot 1b. p_2 in slot 1a. Control lever 41 in $+V_H$ -range. Under these conditions, the regulating pressures derived from p_1 and p_2 displace the piston slider 19e in device SCS toward the left for forming the negative compression angle α_{ka} , and displace the piston slider 19f toward the right for forming the negative expansion angle α_{el} .

Operation type IIIb.—Direction of rotation CL. Operation as motor. Otherwise all settings as mentioned for type IIIa. The negative expansion angle α_{el} becomes a negative compression angle α_{ka} , and the negative compression angle α_{ka} becomes a negative expansion angle α_{ea} .

Operation type IVa.—ACL-rotation. Operation as a pump. p_1 in slot 1a. p_2 in slot 1b. The regulating pressures derived by pressure regulators I and III from p_1 and derived from pressure p_2 by regulators II and IV, produce a displacement of piston slider 19f toward the left for establishing the negative expansion angle α_{el} , and they also cause displacement of piston slider 19f toward the right for forming the negative compression angle α_{ka} .

Operation type IVb.—CL-rotation, Pump operation. All other settings as under IVa. The negative compression angle α_{ka} becomes a negative expansion angle α_{ea} . The elastic means of the switching devices are all of identical design and rating and are so adapted or calibrated as if $V_{el} = V_{ea} = V_s$.

In the hydraulic system according to Fig. 12, two proportional pressure regulators DPR are interposed between lines 46a and 95a on the one hand, and between line 46b and line 95b on the other hand. When applying the system to a high-pressure hydraulic machine, these regulators DPR afford actuating the noise-reducing equipment with a pressure which, though proportional to the pressures p_1 , p_2 , is lower than these. Since with decreasing pressure p_1 or p_2 the reduced proportional pressure must likewise decrease, the proportional pressure regulator DPR, equipped with a stepped piston 98 and a stepped cylinder 97, is provided with an outlet line 52 subjected to negligibly slight pressure. The proportional pressure regulators DPR, of course, may be entirely omitted, and the lines 46a, 46b be directly connected up to the three-way change-over switches CS.

Furthermore, the two change-over switches CS may also be substituted by a single five-way change-over switch or by four individual valves. Furthermore, the proportional pressure regulators DPR may also be substituted by the two-circuit proportional pressure regulators operating with an auxiliary pressure medium supplied from an extraneous pressure source, for instance from the leakage oil pump of the plant, as will be explained below with reference to Fig. 13. It is to be noted, of course, that when using any of the just-mentioned proportional pressure regulators, the elastic means in the slot-control switching devices SCS must have their spring force and characteristic adapted, not to the pressures p_1 and p_2 , but to the proportionally reduced auxiliary pressures.

FIG. 13

Fig. 13 illustrates another example of a complete system comprising the control, switching and regulating devices required for noise reduction in all types of operation. The slot-control switching devices SCS and the rotary slide valve MCV with control slots 1a and 1b correspond, in principle, to the corresponding components shown in Fig. 12.

The regulator housing 36 in the system of Fig. 13 is equipped with four ratio pressure regulators I, II, III, IV similar in principle to those described above with reference to the embodiment of Fig. 8. The control pistons 104 of these regulators are all of the same design. They are displaceably guided in cylinder bores 105 and are each provided with a constriction which, through a piston bore 107, is continuously in hydraulic connection with the uppermost, enclosed cylinder space.

The pistons 104 abut, in pairs, against the two arms of respective teeters 34. Each teeter is pivoted on a swing arm 35 for varying the leverage ratio of the teeter arms and thus the pressure ratio regulated by each pair of regulators. The teeter pivot point can be displaced under control by the above-described control lever 41 actuated in dependence upon the piston-stroke setting selected for the hydraulic machine. For the just-mentioned purpose, the two swing arms 35 of the respective two teeters 34 appertaining to regulators I and II are linked together by a rod 113 and are also linked by a rod 114 to a fork member 75 pivotally mounted in the regulator housing

36 and rigidly joined with the control lever 41. The swing arms 35 of regulators III and IV are likewise linked to the fork members 75 by linking rods 113 and 114. By virtue of these linkages the ratio pressure regulators I and II regulate the angles α_{el} and α_{ea} when the control lever 41 is set into the $+V_H$ -range, while the regulators III and IV simultaneously regulate the angles α_{ea} and α_{ka} respectively. When the system is set for operation in the $-V_H$ -range, the regulators I and II cause the switching devices to regulate the angles α_{ka} and α_{ea} , while the regulators III and IV simultaneously cause the switching devices to regulate the angles α_{el} and α_{ka} . With the illustrated mid-position of control lever 41, corresponding to zero-stroke adjustment of the hydraulic machine, the constrictions 106 of the control pistons 104 in the ratio pressure regulators I and IV are connected through line 95b with control slot 1b, and the constrictions 106 of the control pistons in regulators II and III are connected through line 95a with control slot 1a. A line 66d extends from the constriction 106 of both control pistons 104 in pressure regulator I to the spring space 22d in the slot-control devices SCS; a line 66c connects the constriction in the pistons of the regulator II with the spring space 22c; a line 66a connects the constriction in the pistons of regulator III with the spring space 22a; and a line 66b connects the constrictions in the pistons of regulator IV with the spring space 22b.

In each of the four pressure regulators I, II, III, IV an outlet line 40 under low or atmospheric pressure communicates with the interior of the two cylinder bores 105 of that regulator through respective port openings which

are covered by the lowermost portion of the two control pistons 104 when the control lever 41 is in the illustrated mid-position.

Thus each of the regulating pressure lines 66a to 66d is simultaneously connected through two control ports with the two cylinder bores of each individual ratio pressure regulator, while one of the appertaining control pistons 104 is subjected to one of the pressures p_1 or p_2 from control slot 1a and the other control piston 104 is simultaneously subjected to the other pressure from the control slot 1b, unless the two pistons are subjected, as described above, to respective pressures that are proportionately reduced with respect to p_1 , p_2 .

The performance of the ratio pressure regulators will be described presently with reference to the regulator I, the operation of the three others being similar in principle.

Assume that control lever 41 is in mid-position so that the leverage ratio of the teeter 34 is 1:1. The pressure line 95b connected with control slot 1b communicates with the constrictions of the two respective pistons 104 in regulator I at ports in the vicinity of the upper control edge of the constriction 106. Consequently, the upper enclosed spaces of the two cylinder bores 105 in regulator I are also put under pressure through the piston bore 107. Since the torques produced by the two pistons are equal, the position of the control pistons is at first not changed, and the pressure from line 95b also propagates itself through line 66d to the spring space 22d of the SCS switching device containing the piston slider 19f.

If now the control lever 41 is turned into the $+V_H$ range, the leverage ratio of teeter 34 in regulator I changes in favor of the left-hand control piston 104 and the excess torque produced thereby causes this piston to move down while the right-hand control piston 104 moves up. This continues until the right-hand piston 104 covers the port of line 66d and, during continued lowering of the left-hand piston, also covers the port of the pressure feeder line 95b. This stops the lowering of the left-hand piston, and the pressures above the two control pistons 104 in regulator I now have a ratio inversely related to the effective leverage arms of teeter 34, the pressure above the right-hand piston being always equal to that obtaining in line 95b, and the pressure above the left-hand piston being equal to the regulating pressure transmitted to the line 66d.

If the now obtaining equilibrium is disturbed in favor of the left-hand control piston, as may be due either to further displacement of control lever 41 into the $+V_H$ range or to a pressure drop in control slot 1b, then the left-hand piston 104 in regulator I is displaced a further extent downward; while the switching action at the right-hand control piston remains unchanged despite the simultaneously occurring further lifting of the latter. Ultimately, the left-hand piston moves the lower edge of its constriction 106 below the port opening of the outlet line 40 thus establishing a connection between lines 66d and 40. As a result, the pressure can equalize itself through the left-hand control piston until the latter piston, upon occurrence of torque balance, is again lifted and returns into the illustrated neutral position.

Analogously, a displacement of the lever 41 toward the mid-position or a pressure increase in control slot 1b results in excess torque at the right-hand control piston 104 of regulator I. The latter piston then moves down and the left-hand piston up. The left-hand piston then uncovers the port opening of the feeder line 95b, and the pressure above that piston and hence in line 66d increases until the resulting excess torque causes the left-hand piston to again cover the port opening of the pressure feeder line 95b. During all these regulating operations, the line 95b remains in continuous communication with the constriction 106 of the right-hand control piston.

If now the lever 41, starting from the $+V_H$ position,

is shifted into the $-V_H$ range, then the right-hand control piston acts upon the longer leverage arm and operates, in dependence upon the particular setting of lever 41 and the pressure in control slot 1b, to perform the same regulating functions as were performed in the $+V_H$ range by the left-hand control piston, with the only difference that the regulating pressure in line 66d, previously regulated in accordance with α_{kl} or α_{el} , is now regulated in accordance with α_{ka} or α_{ea} due to the fact that the transmission ratio between the displacing angle of the control lever 41 and the displacement of the pivot axis of teeter 34 has changed.

The same regulating operations take place simultaneously in the pressure regulator II which is coupled with the regulator I, with the only exception that regulator II is subjected to the pressure from control slot 1a and that its two control pistons, depending upon the position of control lever 41, affect the regulating pressure in line 53c. The cooperation of the two regulators I and II has the effect, for instance, that the double-acting piston slider 19f in device SCS, during operation in the $+V_H$ range, has its left end subjected to a regulating pressure derived from the pressure in control slot 1b, while the right-hand end of the same slider 19f is subjected to a regulating pressure derived from the pressure in control slot 1a. The resulting difference force then displaces the piston slider 19f toward the left (since at $+V_H$ the pressure p_2 obtains in control slot 1b) in opposition to the force of the springs loading this piston. The displacement continues until the increasing spring force is in equilibrium with hydraulic difference force.

When changing from pump operation to operation as a motor without change in direction of rotation, the pressures p_1 and p_2 exchange their control slots and, accordingly, the pressures regulated by the regulators I and II change the direction of their pressure drop. Consequently, the piston slider 19f shifts toward the right, which causes the required change of the sign of the angles α_k and α_e respectively.

The performance of the ratio pressure regulators III and IV corresponds to that described above with reference to regulators I and II, with the only difference that the regulators III and IV impose their regulating action through the lines 66a and 66b upon the piston slider 19e of the other component slot-switching device SCS. An examination of the above-described performance in comparison with the possible types of operation listed in the foregoing table will show that the noise reducing system as a whole will always secure the correct operating requirements.

Aside from the foregoing, the embodiment of Fig. 13 is also shown to include a pair of two-circuit proportional pressure regulators DPR similar, in principle, to those described above with reference to Fig. 12 and suitable for use in the system of Fig. 12. Such proportional regulators are necessary or desirable if the pressure liquid required for actuating the regulating devices must not be taken from the hydraulic machine, particularly not from their valve slots. In this case, the additional regulators DPR permit taking an auxiliary pressure medium, for instance from the leakage oil pump, and varying its pressure in such a manner that the series-connected ratio pressure regulators are fed with reduced pressure but in proportion to the respective pressures p_1 and p_2 . By virtue of these devices, no pressure liquid is taken from the control slots of the hydraulic machine, as their respective pressures are utilized only for supplying a control signal to the two-circuit proportional pressure regulators. The operation will be described presently.

The control slots 1a and 1b are connected by respective lines 46a and 46b with one of the two auxiliary regulators DPR. Each of these regulators comprises a stepped cylinder 108 in which a stepped piston 109 is displaceable. The small-diameter piston portions are continuously subjected to the respective pressures p_1

and p_2 in the axial direction and displace the larger-diameter piston portion a sufficient amount to establish a communication between the auxiliary pressure line 89 and the piston constriction 110. Then the auxiliary pressure p can act through the piston bores 111 onto the end surface of the larger piston portion which, due to its large cross section, can in each case again push the entire control piston in opposition to the force of the smaller piston portion, until the further supply of pressure from line 89 is again stopped. If the pressure p_1 or p_2 acting upon the smaller piston declines, the low auxiliary pressure proportional thereto must also decline. This takes place by virtue of the fact that the larger piston portion, acted upon by preponderant force, further displaces the high-pressure piston in the return direction until eventually the outlet line 52, under atmospheric or negligible pressure, enters into communication with the constriction 110. This permits lowering of the pressure in the cylinder end space connected with the constriction through the auxiliary bores 111; and such decline continues until the force of the high-pressure piston again preponderates and returns the stepped piston to the illustrated neutral position. During this regulating operation, the pressure adjusting itself in the large end space of the cylinder always corresponds with satisfactory accuracy to the desired proportional pressure supplied to the ratio pressure regulators I, II, III, IV through the lines 95a and 95b.

For the purposes of the invention, the dimensioning and arrangement of the individual regulating components may be varied in accordance with a large number of possibilities. For example, it is preferable to combine the ratio pressure regulators and all other regulators and switching devices, with the exception of the slot control switch SCS, to a single constructional unit to form the connecting lines as bores, and to use one and the same design of this structural unit without essential change in combination with hydraulic machines which, though of the same type, have different sizes of power ratings. Furthermore, parallel connections of a plurality of hydraulic machines of the same construction may have their slot control devices SCS controlled by a single structural unit of the regulating device just mentioned.

The described noise reducing devices achieve the desired effect by extending the action angle of the pressure commutation in the variable-volume cylinder spaces of the machine, thus prolonging the pressure change over a relatively large angle of rotation of the stroke-producing machine shaft. In some cases it is of advantage to further improve the obtainable noise reduction by providing an even number of cylinders, as is exemplified by Fig. 13 where eight cylinder ports 5 are shown. This results in reducing the alternating force that may excite the housing of the hydraulic machine to oscillations.

The application in practice of the invention does not always require using all components or exactly the same hydraulic circuitry as shown in the above-described embodiments. For example, a hydraulic machine, used for a particular purpose, is not always called upon to satisfy all above-mentioned types of operation. Machines that are to be operated only in the $+V_H$ -range or only in the $-V_H$ -range, need not be equipped with the change-over switches or reversing switches actuated from the piston-stroke control device of the machine, and the above-described special designs of the pressure ratio regulators serving to also perform a change-over or reversing operation may then be omitted. With a certain design of the stroke-producing and volume-changing components of a hydraulic machine operating with variable stroke length, the machine may be equipped with a slot-control switching device simplified by controlling the auxiliary slots on the V_{za} -side of the valve control face only in dependence upon the independent variable $p=p_2-p_1$, and analogously controlling the auxiliary slots on the V_{zi} -side only in dependence upon the independent variables $p=p_2-p_1$ and

$V_H/V_{H\max}$. Furthermore, depending upon the particular requirements, the various described types of proportional pressure regulators can be exchanged for each other or can be entirely omitted. A mutual exchange, without affecting the desired operation, is also possible relative to the switching devices according to Figs. 3 to 5, and, to a limited extent, also relative to the switching devices according to Fig. 6. The design of the ratio pressure regulators can be given a variety of forms, without change in operation, and can be adapted to the chosen other components of the machine, without departing from the desired noise reducing performance in accordance with the principles and essential features of the invention disclosed herein.

15 I claim:

1. In combination with a rotary hydraulic multi-cylinder machine, a noise reducing device, comprising a rotary main control valve having two coating valve members of which one has arcuate and concentrically sequential control slots for respectively different pressures when in operation, and the other valve member has ports communicating with the respective machine cylinders and alternately registering with said control slots; each of said control slots having its ends subdivided and forming thereby a main slot and a number of serially adjacent auxiliary slots individually shorter than said main slot; slot-switching means, hydraulic line means respectively connecting said slot-switching means with said respective auxiliary slots and with said main slot; said slot-switching means being connected hydraulically in series with said line means for progressively connecting and disconnecting said auxiliary slots relative to said main slot, whereby said slot-switching means vary the effective angular length of said control slots in noise reducing sense.

2. In combination with a rotary hydraulic multi-cylinder machine, a noise reducing device, comprising a rotary main control valve having two coating valve members of which one has arcuate and concentrically sequential control slots of different respective pressures when in operation, and the other valve member has ports communicating with the respective machine cylinders and alternately registering with said control slots; each of said control slots having its ends subdivided and forming thereby a main slot and a number of serially adjacent auxiliary slots individually shorter than said main slot; slot-switching means, hydraulic line means respectively connecting said slot-switching means with said respective auxiliary slots and with said main slot; said slot-switching means being connected hydraulically in series with said line means for progressively connecting and disconnecting said auxiliary slots relative to said main slot, said switching means being connected with said two main slots and responsive to the pressure difference of said respective main slots, whereby said switching means automatically control the effective angular length of said control slots in noise reducing sense.

3. A rotary hydraulic machine comprising a multiplicity of simultaneously rotating cylinders each having a piston reciprocable therein, said pistons having each an inner 60 and an outer dead-center position defining together a fixed neutral axis, a rotary main valve having two coactive valve members of which one rotates together with said cylinders and has respective ports concentrically distributed and communicating with said cylinders, the other 65 valve member being fixed and having two arcuate and concentrically sequential control slots for pressure and suction with which said ports alternately communicate, said two control slots being symmetrically located on opposite sides respectively of said neutral axis; each of said 70 control slots having both of its ends subdivided and forming a main slot and two serially adjacent groups of auxiliary slots individually shorter than said main slot; multiple slot-switching means, hydraulic line means respectively connecting said slot-switching means with each of said 75 main slots and with each of said respective auxiliary slots

of said two adjacent groups; said multiple slot-switching means being connected hydraulically in series with said line means for progressively connecting and disconnecting said auxiliary slots relative to said main slot, whereby said switching means control the effective angular length of said control slots in noise reducing sense.

4. In a hydraulic machine according to claim 3, said slot-switching means having displaceable actuator members hydraulically connected to said two main slots and responsive to the pressure difference of said main slots whereby said slot-switching means automatically regulate the angle of rotation during which said ports are connected with said respective control slots so that, with motor operation of the machine, said ports communicate with the pressure slot from said inner dead-center position up to the regulated angle ahead of said outer dead-center position and said ports communicate with the suction slot from said outer dead-center position up to the regulated angle ahead of said inner dead-center position, whereas, at pump operation of the machine, said ports communicate with the pressure slot after elapse of the regulated angle behind the inner dead-center position up to said outer dead-center position and thereafter communicate with the suction slot from the elapse of the regulated angle behind the outer dead-center position up to the inner dead-center position.

5. In a hydraulic machine according to claim 1, said machine having constant piston stroke, and said slot-switching means being dependent upon the delivery pressure and delivery direction of the machine for automatically regulating the effective angular extent of said control slots as to sign and magnitude.

6. In a hydraulic machine according to claim 1, said machine having variable piston-stroke length, said slot-switching means having control means responsive to the delivery pressure, the stroke ratio and the type of machine operation as regards correlation of direction of rotation and direction of delivery, whereby said control means actuate said slot-switching means to automatically regulate the effective angles of said control slots as to sign and magnitude.

7. In a machine according to claim 3, said slot-switching means comprising four individually operable hydraulic switch devices each connected with one of said four respective groups of auxiliary slots, each of said four switch devices having an actuating member connected with said two main slots and responsive to the pressure difference of said two main slots.

8. In a machine according to claim 3, said slot-switching means comprising two individually operable hydraulic switch devices, each of said switch devices being common to those two of said auxiliary slot groups that are next to each other on opposite sides respectively of said neutral axis, and each of said two switch devices having an actuating member connected with said two main slots and responsive to the pressure difference of said two main slots.

9. In a machine according to claim 3, said slot-switching means comprising two individually operable hydraulic switch devices, each of said switch devices being common to two of said auxiliary slot groups located at the two ends of one and the same main slot, and each of said two switch devices having an actuating member connected with said two main slots and responsive to the pressure difference of said two main slots.

10. In a machine according to claim 3, said slot-switching means comprising a single displaceable hydraulic actuator connected with said two main slots and displaceable in dependence upon the pressure difference of said two main slots, whereby all four groups of auxiliary slots are jointly controlled by said one actuator.

11. In combination with a rotary hydraulic multi-cylinder machine, a noise reducing device, comprising a rotary main control valve having two mutually coacting valve members of which one has arcuate and concentrically sequential control slots of different respective pressures

when in operation, and the other valve member has ports communicating with the respective machine cylinders and alternately registering with said control slots; each of said control slots having its ends subdivided and forming thereby a main slot and two groups of serially adjacent auxiliary slots; hydraulic lines extending between each of said main slots and said respective adjacent auxiliary slots; slot-control switch means hydraulically in series with said lines and displaceable in two directions for progressively connecting and disconnecting said auxiliary slots relative to the adjacent one of said main slots thus varying the active angular length of said control slots; control means connecting said slot-control switch means with said two main slots for displacing said switch means in dependence upon the pressure difference of said two main slots; and elastic biasing means connected with said slot-control switch means and having a biasing direction opposed to the effect of said pressure difference, whereby the relation of said pressure difference to the resulting regulated angular length of said control slots is dependent upon the force-displacement characteristic of said elastic means.

12. In a device according to claim 11, said slot-control switch means comprising an axially displaceable multi-way valve slider and a valve sleeve in which said slider is displaceable in opposition to the force of said elastic means, said sleeve having lateral ports axially spaced from each other and individually connected through said respective lines with the main slot and with one of said groups of auxiliary slots adjacent to said one main slot so that displacement in a given direction of said slider causes said main slot to communicate with a progressively changing number of said auxiliary slots.

13. In a device according to claim 12, said switch control means comprising two hydraulic lines connecting said sleeve with said two main slots at opposite sides respectively of said slider whereby the two pressures of said respective main slots opposingly act upon said slider for displacing it in said sleeve, said elastic means comprising a spring mounted in said sleeve and biasing said slider toward the side of the higher slot pressure; said spring having increasing spring force with increasing displacement.

14. In a device according to claim 11, said control means comprising differential hydraulic means connected with said two main slots and subject to the respective pressures in said main slots, said hydraulic means having an output pressure dependent upon the difference of said two slot pressures; and said slot-control switch means comprising a multi-way valve slider and a valve sleeve in which said slider is displaceable, said sleeve having lateral ports axially spaced from each other and individually connected through said respective lines with the main slot and a group of said adjacent slots of one or said control slots so that displacement in a given direction of said slider causes said main slot to communicate with a progressively changing number of said auxiliary slots; said hydraulic means being connected with said valve sleeve at one side of said slider for imposing said output pressure upon said slider, pressure-escape duct means connected to said sleeve at the opposite side of said slider, whereby said slider is displaced by said pressure output in dependence upon the difference of said two slot pressures; said elastic biasing means having relative to said slider a biasing direction opposed to said output pressure and having a force increasing with increasing slider displacement.

15. With a rotary hydraulic multi-cylinder machine having variable piston stroke and having a displaceable stroke control member, the combination of a noise reducing device comprising a rotary main control valve having two interacting valve members of which one has arcuate and concentrically sequential control slots of different respective pressures when in operation, said other valve member having ports communicating with

the respective machine cylinders and alternately registering with said control slots, each of said control slots having its ends subdivided and forming thereby a main slot and two groups of serially adjacent auxiliary slots; slot-switching means, hydraulic line means respectively connecting said slot-switching means with said respective auxiliary slots and with said main slot; said slot-switching means being connected hydraulically in series with said line means for progressively connecting and disconnecting said auxiliary slots relative to said main slot; ratio regulator means connected with said respective main slots and having an output magnitude varying in a given ratio to the difference of the respective pressures of said main slots, said regulator means having an adjustable ratio control device connected with said stroke control member for varying said ratio in a given dependence upon the setting of said stroke control member; and actuating means connecting said slot-switching means with said ratio regulator means for controlling said slot-switching means by said ratio-dependent control magnitude.

16. In combination with a rotary hydraulic multi-cylinder machine, a noise reducing device, comprising a rotary main control valve having two interacting valve members of which one has arcuate and concentrically sequential control slots of different respective pressures when in operation, said other valve member having ports communicating with the respective machine cylinders and alternately registering with said control slots, each of said control slots having its ends sub-divided and forming thereby a main slot and two groups of serially adjacent auxiliary slots; slot-switching means, hydraulic line means respectively connecting said slot-switching means with said respective auxiliary slots and with aid main slot; said slot-switching means being connected hydraulically in series with said line means for progressively connecting and disconnecting said auxiliary slots relative to said main slot; a differential pressure device having two duct lines connected with said respective main slots and having an output magnitude proportional to the difference of the respective pressures in said two slots; ratio regulator means connected to said differential pressure device and controlled by said output magnitude to provide a control magnitude in a given proportion to said slot-pressure difference, said ratio regulator means having adjustable control means for varying said ratio in accordance with a desired performance of the hydraulic machine; and actuating means connecting said slot-switching means with said ratio regulator means for controlling said slot-switching means by said ratio-dependent control magnitude.

17. In a device according to claim 16, said hydraulic machine having a variable piston stroke and having a control structure displaceable in accordance with the desired stroke, said control structure being coupled with said control means of said ratio regulator, whereby said slot-switching means is controlled in dependence upon said slot-pressure difference as well as upon the selected stroke setting of the machine.

18. A rotary hydraulic machine comprising a multiplicity of simultaneously rotating cylinders each having a piston reciprocable therein, said pistons having each an inner and an outer dead-center position defining together a fixed neutral axis, a rotary main valve having two active valve members of which one rotates together with said cylinders and has respective ports concentrically distributed and communicating with said cylinders, the other valve member being fixed and having two arcuate and concentrically sequential control slots of respectively different pressures with which said ports alternately communicate, said two control slots being symmetrically located on opposite sides respectively of said neutral axis; each of said control slots having both of its ends subdivided and forming a main slot and two serially adjacent groups of auxiliary slots, said four groups of auxiliary slots being located in respective four quadrants of valve rotation; slot-switching means, hydraulic line means respec-

tively connecting said slot-switching means with each of said main slots and with each of said respective auxiliary slots of the two groups adjacent to said main slot; said slot-switching means having displaceable valve structure hydraulically connected in series with each of said respective line means for connecting and disconnecting said auxiliary slots in each group with the adjacent one of said main slots whereby displacement of said valve structure varies the effective angular length of said control slots; control means connected to said respective main slots and responsive to the respective pressures of said main slots, said control means being connected with said valve structure for displacing said valve structure in dependence upon the difference of said pressures; said slot-switching means having spring means biasing said valve structure in opposition to displacement caused by said control means; the spring means coordinated to said auxiliary slot groups in the two quadrants adjacent to said inner dead-center position having a different spring force-displacement characteristic than said spring means coordinated to said two quadrants adjacent said outer dead-center position, the difference in spring characteristics being substantially in accordance with the difference in the cylinder volumes of the machine at inner and outer dead-center positions respectively.

19. In a machine according to claim 15, said slot-switching means comprising independently actuatable slot-switch components hydraulically correlated to different ones of said groups of auxiliary slots; said ratio regulator means comprising component regulators in controlling connection with said respective switch components and having said adjustable ratio control device in common; and line-switch means operably connected between said regulators and said slot-switch components for exchanging said regulators relative to said slot-switch components, said line-switch means having hydraulic control means connected with said two main slots for actuating said line-switch means in dependence upon the direction of the pressure difference of said two main slots.

20. In a machine according to claim 15, said slot-switching means comprising independently actuatable slot-switch components hydraulically correlated to different ones of said groups of auxiliary slots; said ratio regulator means comprising component regulators in controlling connection with said respective slot-switch components and having said adjustable ratio control device in common; and line-switch means operably connected between said regulators and said slot-switch components for exchanging said regulators relative to said slot-switch components, said line-switch means being connected with said adjustable ratio control device to be controlled jointly with said regulators.

21. A machine according to claim 19, comprising a differential pressure regulator interposed between said respective main slots and said ratio regulator means and differentially responsive to the pressures of said respective main slots whereby said regulator means receive from said differential pressure regulator a control pressure proportional to said difference; said slot-switch components having each a displaceable valve slider of which one side is connected to one of said respective ratio regulators to be subject to control by the output magnitude of said regulator, the respective other sides of said valve sliders being under substantially atmospheric pressure.

22. In a machine according to claim 15, said slot-switching means comprising independently actuatable slot-switch components hydraulically correlated to different ones of said groups of auxiliary slots; said ratio regulator means comprising component regulators in controlling connection with said respective switch components and having said adjustable ratio control device in common; and line-switch means operably connected between said ratio regulators and said respective main slots for exchanging the slot connection of said regulators, said line-switch means

being connected with said adjustable ratio control device to be controlled jointly with said regulators.

23. In a machine according to claim 15, said slot-switching means comprising independently actuatable slot-switch components hydraulically correlated to said respective groups of auxiliary slots; said ratio regulator means comprising component regulators in controlling connection with said respective slot-switch components; and said adjustable ratio control device comprising non-linear transmission means connected with said stroke control member so as to vary said ratio in accordance with a given non-linear law of dependence upon the displacement of said stroke control member, said ratio control device being coupled with said regulators so as to render them selectively operative in dependence upon the direction of displacement of said stroke control member from its zero-stroke position.

24. In a machine according to claim 16, said slot-switching means comprising independently actuatable slot-switch components hydraulically correlated to different ones of said groups of auxiliary slots; said ratio regulator means comprising component regulators in controlling connection with said respective switch components and having said adjustable ratio control device in common; and a reversing switch connected between said differential pressure device and said regulators for selectively supplying said output magnitude to said respective regulators in dependence upon the direction of said slot-pressure difference.

25. In a machine according to claim 24, said reversing switch and said differential pressure device forming together a single hydraulic multi-way switch and comprising a valve sleeve and a valve slider displaceable in said sleeve, said valve sleeve having its respective ends connected to said two main slots for controlling the slider displacement in dependence upon said slot-pressure difference, and said valve slider having a plurality of constricted portions forming said reversing switch.

26. In a machine according to claim 25, said valve slider of said multi-way switch having a middle part and two end parts of smaller diameter than said middle part to provide for differential-pressure regulating operation, and said constricted portions being located in said middle part.

27. In a machine according to claim 15, said slot-switching means comprising independently actuatable slot-switch components hydraulically correlated to different ones of said groups of auxiliary slots; said ratio regulator means comprising two component regulators in controlling connection with said respective switch components and having said adjustable ratio control device in common; each of said regulators comprising two control pistons and a pivoted teeter abutted by said two pistons on opposite sides of the teeter pivot point so as to balance said two pistons against each other, one of said two pistons being loaded by pressure dependent upon at least one of said two main-slot pressures and the other piston being connected with the regulator output so as to be loaded by said regulated ratio-dependent control magnitude; and said ratio control device having means connected with said teeter for displacing the teeter pivot point in a given dependence upon the setting of said stroke control member.

28. A machine according to claim 27, comprising a carrier member on which said teeter is pivoted, said carrier member forming part of said ratio control device and being displaceable in both directions from a mid-position in which said teeter has a one-to-one leverage ratio relative to said two control pistons of said regulator.

29. In a machine according to claim 15, said slot-switching means comprising independently actuatable slot-switch components hydraulically correlated to different ones of said groups of auxiliary slots; said ratio regulator means comprising two component regulators in controlling connection with said respective switch components and having said adjustable ratio control device in common; each of said regulators comprising two control pistons

and a pivoted teeter abutted by said two pistons on opposite sides of the teeter pivot point so as to balance said two pistons against each other, a carrier member on which said teeter is pivoted, said carrier member forming part of said ratio control device and being displaceable in both directions from a mid-position in which said teeter has two substantially equal leverage arms relative to said two control pistons, whereby either one of said arms becomes longer than the other when said carrier member is displaced from said mid-position; control switch means connected with and controlled by said ratio control device and hydraulically interposed between said regulators and said main slots so as to connect and load in each regulator the one piston that acts upon the longer teeter arm with the regulator output magnitude regulated by said one piston, while simultaneously connecting and loading the other piston with a pressure dependent upon said difference of said main-slot pressures.

30. In the machine according to claim 29, said control switch means having displaceable hydraulic switch members integral with said respective control pistons of said regulator, each of said regulators having a control cylinder in which one of said respective control pistons is displaceable, and each of said control cylinders having lateral ports to be covered and uncovered by said control piston to operate as said control switch means.

31. In a machine according to claim 16, said differential pressure device comprising a valve cylinder having a middle portion of large diameter and two side portions of small diameter coaxially adjoining both ends of said middle portion, and a composite valve piston axially displaceable in said valve cylinder and having a large-diameter middle portion and two small-diameter side portions in said respective middle and side portions of said valve cylinder; said two cylinder side portions being hydraulically connected with said respective main slots for displacing said valve piston in accordance with the pressure difference of said main slots; said piston middle portion and said cylinder middle portion forming together two annular chambers on axially opposite sides of said piston middle portion when said piston is in mid-position; a pressure relief line having two lateral ports in said respective annular chambers at points close to said piston middle portion so that either port is covered when said piston middle portion is displaced from said mid-position; a connecting line connecting each of said annular spaces, at a point spaced from said pressure relief port of the same chamber, with the one cylinder side portion remote from said chamber at a point of said latter portion normally covered by the adjacent piston side portion, said connecting line having a pressure corresponding to said pressure difference; whereby the displacement of said valve piston from said mid-position first causes covering of one of said relief ports in the one annular chamber of diminishing volume and thereafter opening of said connecting line leading from said latter chamber to the one cylinder side portion then under pressure from one of said respective main slots, while the other annular chamber and the other connecting line are then in communication with the other relief port.

32. In a machine according to claim 31, said piston middle portion having a cross-sectional area more than twice as large as the cross-sectional area of said piston side portions to make the regulated pressure of said differential pressure device a proportional fraction of the pressure difference of said respective main slots.

33. In a machine according to claim 31, said slot-switching means comprising independently actuatable slot-switch components hydraulically correlated to different ones of said groups of auxiliary slots; said ratio regulator means comprising component regulators in controlling connection with said respective switch components and having said adjustable ratio control device in common; a reversing switch hydraulically interposed between said

differential pressure device and said regulators for selectively supplying said output magnitude to said respective regulators in dependence upon the direction of said slot-pressure difference, said reversing switch being mechanically an integral part of said differential pressure device and being formed of constrictions of said piston middle portion and of additional valve ports of said valve cylinder, said latter ports being controlled by said constrictions.

34. In a machine according to claim 16, said differential pressure device comprising two hydraulic circuits, one of said circuits including said two duct lines for controlling said differential pressure device in dependence upon said slot-pressure difference, said other hydraulic circuit comprising auxiliary pressure-medium supply lines for connection to an extraneous pressure source and being connected with said ratio regulator means, whereby said output magnitude is supplied by said auxiliary supply lines under control by said slot-pressure difference.

35. In a machine according to claim 16, said slot-switching means comprising independently actuatable slot-switch components hydraulically correlated to different ones of said groups of auxiliary slots; said ratio regulator means comprising component regulators in controlling connection with said respective switch components and having said adjustable ratio control device in common; said differential pressure device comprising two hydraulic circuits, one of said circuits including said two duct lines for controlling said differential pressure device in dependence upon said slot-pressure difference, said other hydraulic circuit comprising extraneous-pressure supply lines and being connected with said ratio regulator means, whereby said output magnitude is supplied by said pressure supply lines under control by said slot-pressure difference; a reversing switch hydraulically connected between said differential pressure device and said regulators for selectively supplying said output magnitude to said respective regulators in dependence upon the direction of said slot-pressure difference; said two-circuit differential pressure device and said reversing switch forming together a single hydraulic multi-way valve having a single valve piston displaceable in dependence upon said slot-pressure difference.

36. A rotary hydraulic machine comprising a multiplicity of simultaneously rotating cylinders each having a piston reciprocable therein, said pistons having each an inner and an outer dead-center position defining together a fixed neutral axis, a rotary main valve having two co-active valve members of which one rotates together with said cylinders and has respective ports concentrically distributed and communicating with said cylinders, the other valve member being fixed and having two arcuate and concentrically sequential control slots of respectively different pressures with which said ports alternately communicate, said two control slots being symmetrically located on opposite sides respectively of said neutral axis; each of said control slots having both of its ends subdivided and forming a main slot and two serially adjacent groups of auxiliary slots, said four groups of auxiliary

slots being located in respective four quadrants of valve rotation; slot-switching means, hydraulic line means respectively connecting said slot-switching means each of said main slots and with each of said respective auxiliary slots of the two groups adjacent to said main slot; said slot-switching means having displaceable valve structure hydraulically connected in series with each of said respective line means for connecting and disconnecting said auxiliary slots in each group with the adjacent one of said main slots whereby displacement of said valve structure varies the effective angular length of said control slots; control means connected to said respective main slots and responsive to the respective pressures of said main slots, said control means being connected with said valve structure for displacing said valve structure in dependence upon the difference of said pressures; two pairs of ratio regulators each having a regulated output pressure varying in a given ratio to the difference of the respective pressures of said main slots, one regulator of each pair having pressure input means hydraulically connected with one of said respective main slots, and the other two regulators having pressure input means hydraulically connected with the other main slot, means connecting said two output pressures of one of said pairs in mutually opposed relation to the said valve structures of the slot-switching means for the two auxiliary slot groups adjacent to said inner dead-center position, and means connecting said two output pressures of the other regulator pair in mutually opposed relation to said valve structures of the slot-switching means for the two auxiliary slot groups adjacent to said outer dead-center position; a ratio control device connected with said two pairs of regulators and having a displaceable control member for varying said ratio in each regulator in dependence upon a desired machine performance, and respective transmission means interposed between said displaceable control member and said respective pairs of regulators and having respectively different laws of dependency of said ratios upon a given displacement of said latter member.

37. A machine according to claim 36, comprising reversing switch means hydraulically connected between said four regulators and said valve structures of said slot-switching means for exchanging said output pressures relative to said valve structure; said reversing switch means forming integral parts of said regulators so as to be actuated together with the ratio control of said regulators in response to displacement of said member of said ratio control device.
